UNITED STATES PATENT OFFICE

HERBERT M. FRIENDLY AND ARCHIBALD E. BURNS, OF PORTLAND, OREGON; SAID BURNS ASSIGNOR TO SAID FRIENDLY, MILTON S. FRIENDLY, AND CENTRAL REPUBLIC BANK AND TRUST COMPANY, EXECUTORS OF SAID HERBERT M. FRIENDLY, DECEASED

TOLL TELEPHONE SWITCHING APPARATUS

Application filed June 11, 1915, Serial No. 531,310. Renewed January 23, 1922.

A feature of this invention relates to the means and methods whereby an operator, hereinafter for convenience to be designated as the manual toll operator at a remote station, hereinafter to be designated, for convenience, as the manual exchange, may secure a connection over a toll line with a subscriber in an exchange of the well known automatic type, hereinafter to be designated, for convenience as the automatic exchange, by the operation of apparatus under the control of the operator, and the operator may signal the called subscriber by the well known method of ringing, and may release the connection at will, all without the agency or assistance of any person at the automatic exchange or associated toll board.

Further, a feature of this invention relates to the display of signals at the toll switchboard associated with the automatic exchange, and which for convenience will hereinafter be designated as the automatic toll board, whereby the operators at said toll switchboard may be apprised of the fact that a remote operator is securing connection with a local subscriber in the automatic exchange proper by the use of the means hereinafter to be described.

Further, a feature of this invention relates to the use of a recording device of the well known tape or other type whereby there is indicated or recorded information as to the number of the called line, time of day, duration of conversation, and other details as desired.

Further, a feature of this invention relates to means and methods whereby an operator at the toll switchboard associated with the automatic exchange, said operator hereinafter for convenience to be designated as the automatic toll operator, may by means under said operator's control secure connection with a subscriber's line in the manual exchange directly through the agency of the operator at the "B" board in the manual exchange, but without the agency or assistance of any one at the manual toll board associated with the manual exchange. Said "B" board and its functions are well known in the art and need not be described.

Further, a feature of this invention relates to the display of signals at the manual toll board to indicate to the manual toll operators the fact that a telephonic connection is being made to a subscriber's line, or such a service is underway, with the toll line, through the "B" board.

Further, a feature of this invention relates to the use of means whereby the springjacks of the manual toll board, which are normally associated with the toll line, are disconnected therefrom as soon as the automatic toll operator has started the operation of securing a connection through the "B" board.

Further, a feature of this invention relates to means and methods whereby an operator at a station situated on the toll line somewhere between the manual exchange and the automatic exchange, and which for convenience will be designated as the intermediate toll station, may secure connection with a subscriber's line in the automatic exchange by the use of means similar to that employed by the manual toll operator in doing likewise. Simultaneously the portion of the toll line leading to the automatic exchange may be disconnected from that portion of the toll line from the intermediate station to the manual exchange.

Further, a feature of this invention relates to the means and method whereby the intermediate toll operator may secure connection with a subscriber's line in the manual exchange through the "B" board in a manner similar to that previously outlined, whereby the automatic toll operator secured connection with a local subscriber's line in the manual exchange through the "B" board. Simultaneously, that portion of the toll line from the intermediate station to the manual exchange may be disconnected from that portion of the toll line from the intermediate station to the automatic exchange.

Further, a feature of this invention is that a connection may be made from the intermediate station to a subscriber's line in the manual exchange through the "B" board simultaneously with a connection with the intermediate station to the subscriber's line in the automatic exchange, by the means pro-

vided for automatically calling from the intermediate station, neither operation nor the attendant telephonic service interfering with the other.

5 Further, a feature of this invention relates to means whereby signals on the toll line are caused to be displayed at signal devices thereon by any of the well known means of projecting current to actuate such devices, 10 incidentally causing the signals to display at the intermediate toll boards.

One signal device displays constantly until released by the insertion of a switching plug in the associated springjack, while the other 15 displays with each signal impulse applied, thus the latter enables the operator to ascertain what code signal is being transmitted over the toll line.

Further, a feature of this invention relates 20 to the means provided and methods of operation of a cord circuit for use in a manual toll board and in the intermediate toll board wherein one side of the circuit or otherwise the circuits directly associated with one of 25 the plugs of the pair provides means for connecting with a local subscriber's line, while the other side provides means whereby connection may be had with the toll line.

Further, a feature of this invention provides 30 means for ringing or signaling on the toll line in the well known usual manner, irrespective of auxiliary equipments or methods of operation other than those well known in the art.

35 Further, a feature of this invention provides means for connecting at will a calling device of the well known automatic type with the toll line in the proper manner to actuate the apparatus at the automatic exchange to 40 secure connection with a local subscriber's line.

Further, a feature of this invention provides 45 means for transmitting the proper impulses on the toll line to actuate the apparatus at the automatic exchange to ring or signal on the called subscriber's line in the well known and usual manner.

Further, a feature of this invention relates 50 to the employment in the circuits of the well known telephonic apparatus, known as a repeating coil, intermediate between the toll line and the apparatus connected thereto in the above mentioned relation for the purposes 55 of preventing an unbalancing of the toll line in the usually accepted telephonic sense. This is in order to prevent such reaction of the apparatus on the toll line as to render it more or less noisy to the detriment 60 of telephonic transmission.

Further, a feature of this invention is that the toll line may be used for the purpose of 65 signaling and for transmitting telephonic communication in the manner commonly in use and well known in the art, the addition

of this apparatus not interfering with such common usage.

Further, a feature of this invention relates to the means whereby grounded ringing or signaling current and other abnormal electrical conditions commonly met with in practice are prevented from interfering with the proper functioning of any of the apparatus. 70

There are many other features and details of the circuits and apparatus, and the operating of same, that have not been specifically mentioned hereinbefore. Some of these will be mentioned or referred to hereinafter; also there are many other modifications subordinate to our invention that will occur to those skilled in the art to which our invention belongs. These modifications may be readily made and adapted to the various practical uses to which such equipment is applicable. Therefore, this invention is not limited to the particular arrangements of circuits shown, but it has a wide application through modification and amplification without departing from its scope. The various conditions of terminal, exchange and other apparatus and the methods of operation and traffic will necessarily require modifications and adaptation. The drawings hereto attached and the descriptions of same show one organization of circuits and apparatus for accomplishing results under one particular set of conditions and are simply used as illustrative of our invention. 85 90 95

In the drawings:

Figure 1 is a circuit diagram of apparatus 100 at the manual exchange.

Figure 2 is a circuit diagram of apparatus at the intermediate station.

Figure 3 is a circuit diagram of apparatus at the automatic exchange. 105

Figure 4 illustrates the line from the automatic toll board to the automatic exchange and to the automatic subscriber's station.

Figure 5 is a circuit diagram of a cord circuit for use at the manual toll board and at the intermediate toll board for connecting with a subscriber's line in the usual manner; also for connecting independent lines to the toll line in the usual manner commonly accomplished with cord switching pairs; also 110 means whereby a calling device may be connected with the toll line in such manner as to make it possible to automatically select a subscriber's line in the distant automatic exchange; also means for ringing or signaling the called subscriber. 115 120

Figure 6 is a diagrammatic representation of the toll line and associated equipment.

The illustrations used for equipment and apparatus in the above referred to drawings 125 are diagrammatic and conventional and do not purport to represent structural details.

In Figure 6, A and B represent the terminals of a toll line at the manual exchange designated F1. C and D, and E and F, re- 130

spectively, represent the terminals of the sections of the toll line at the intermediate exchange or station designated F2. G and H represent the terminals of the toll line at the automatic exchange. I and J are the terminals of the associated springjack on the automatic toll board. K and L are the terminals of the first of the automatic selecting devices at the automatic exchange, commonly known as a first selector, while M and N are the terminals of the subscriber's line circuit at the last automatic selecting device in a five-digit automatic telephone exchange.

The automatic exchange is the well known type contemplated in U. S. patent to Keith, Erickson and Erickson, #815,321, granted March 13, 1906, and the U. S. Patent #815,176 granted to Keith, Erickson and Erickson, March 13, 1906. Specific automatic exchange embodiments of the said type are those installed by the Automatic Electric Company of Chicago, Illinois, at Portland, Oregon; Tacoma, Washington, and Bellingham, Washington, during the years 1906 to 1908, and used over a period of years thereafter. This specific embodiment of automatic systems is known as the three-wire common battery automatic system.

In Figure 4, the springjack J20 and its terminals I' and J', the automatic selecting device R35—R36, and the subscriber's equipment S2, are shown diagrammatically in a somewhat fuller form than in Fig. 6.

The following are various conditions of service between the several stations and exchanges on the toll line, in the case chosen for description, the methods of operation of which will be hereafter described in detail:

a. Where the automatic toll operator executes a telephonic connection over the toll line to a subscriber's line in the manual exchange through the "B" board at the latter exchange.

b. Where the manual toll operator executes a telephonic connection over the toll line to a subscriber's line in the automatic exchange through the use of an automatic calling device at the manual toll board.

c. Where the intermediate toll operator executes a telephonic connection over the toll line to a subscriber's telephone in the manual exchange through the "B" board at the latter exchange.

d. Where the intermediate toll operator executes a telephonic connection over the toll line to the subscriber's line by the use of an automatic calling device at the intermediate station.

e. Where any station on the line signals any other station on the line or executes a telephonic connection in the manner commonly used and well known in the art.

Referring to paragraph a: The automatic toll operator desiring to secure a connection through the "B" board, ascertains first that

the line is not busy, by noticing that none of the multiplied busy lamps e22, e23, e29, e32, e26 and e35, Fig. 3, are glowing, as would be the case if a plug as P2, Fig. 5, were inserted in any of the jacks J14, J15, J16, J17, J18 and J19. The operator then inserts plug as P2, Fig. 5, in jack J16 or either of its multiples J14 and J15, and ascertains if the line is busy at any other station, by listening in the usual manner. As a matter of fact, the cord circuit used could differ from Fig. 5 in many respects, being a common form of toll to automatic cord circuit, for instance, but it is not an essential part of this invention considered alone, so the circuit shown in Fig. 5 answers all purposes of description and illustration. The line being found free, the operator inserts plug into jack J18, or either of its multiples J17 or J19. This completes a circuit from ground G5, Fig. 5, through contacts 180—181, contacts k17—k16; sleeve of plug; sleeve of jack, Fig. 3, through relay R29 to battery B3; also, a parallel or derived circuit from sleeve of jack through relay R34 to battery B3. Relay R29 operates, breaking contacts 152—153 and 155—156, disconnecting the toll line on terminals G and H from the apparatus for automatic calling (which will be described later), and connects it with the apparatus for calling and connecting through the "B" board at the manual exchange. Current now flows from main battery B3 through the windings of relays R32 and R31 in series; then divides through two paths in parallel, one path being through repeating coil winding C22—C21 through contacts 157—156 to terminal G of the toll line; over toll line conductor to terminal A, Fig. 1; through contacts 34—35; through contacts 11—12; through winding C6 of repeating coil. The other parallel or derived path is through repeating coil windings C23—C24; through contacts 154—153 to the terminal H of toll line; over toll line conductor to terminal B, Fig. 1; through contacts 37—38; through contacts 14—15; through winding C8 of repeating coil, where it unites with the current in the other branch; thence through relay R8; through contacts 50—49 to ground G1. This current actuates relays R31 and R32, Fig. 3, and relay R8, Fig. 1. Current flows from battery B3, through lamps e27, e30, e33 in parallel; thence through contacts 159—158 to ground G3, glowing the lamps and indicating to the automatic toll operator that the "B" operator at the manual exchange, Fig. 1, is on the line.

Relay R8 being operated, current flows from battery B1 through relay R3; through contacts 53—52 to ground G1, actuating relay R3, which disconnects the signal device D1 by opening contacts 19—20 and 21—22; opens the circuit of relay R2 by virtue of opening contacts 24—23; closes circuit from ground G1 through contacts 17—18—18'; through

lamps $e2$, $e4$, $e6$, $e8$, $e10$, $e11$, all in multiple to battery $B1$, glowing them and thus indicating that the distant automatic toll operator is securing a connection through the "B" board. Relay $R3$ also closes a circuit from ground $G1$ through contacts $17-18$; through contacts $3-4$; through contacts $43-42$; through lamp $e2'$; through sounder $S3$ to battery $B1$, glowing the lamp $e2'$ and thus apprising the "B" operator that a call is to be placed by way of her board, the sounder $S3$ attracting her attention audibly as well. A parallel or derived circuit is from ground $G1$ through contacts $17-18$; through contacts $51'-51$; through relay $R6$ to battery $B1$. This actuates relay $R6$, which completes a talking circuit from the "B" operator's telephone circuit $S2$ through contacts $44-45$ and $46-47$; through repeating coil windings $C5$ and $C7$ and the condenser 199 . As the windings $C5-C7$ are in inductive relation to windings $C6-C8$, this allows the automatic toll operator to talk directly to the "B" operator over the line and request a connection with the desired subscriber's line in the manual exchange.

The talking connection at the automatic toll board may be traced from the spring-jacks $J17$, $J18$ or $J19$ through contacts $154-153$ and $157-156$ to line terminals G and H . Returning to Fig. 1, the "B" operator inserts plug $P1$ in a subscriber's line jack $J7$ (or an intermediate trunking jack). Current then flows from battery $B1$ through relay $R9$ to sleeve of jack; through sleeve of plug, through relay $R7$ to ground $G1$. This actuates relay $R7$ and thereby disconnects the ground $G1$ from contact 50 and the upper terminal of relay $R8$, however, leaving relay $R8$ grounded through the resistance $T1$. Current now flows from ground $G1$ through contacts $49-48$; through contacts $7-6$; through lamp $e1'$; through the sounder $S3$ to battery $B1$, causing the latter lamp to also glow. Contacts $51-51'$ break, opening the circuit of relay $R6$, allowing it to return to its normal position and thereby disconnect the "B" operator's telephone connections on contacts $44-45$ and $46-47$. The extra resistance $T1$ in the circuit decreases the current to a point where relay $R32$, Fig. 3, returns to normal position and thereby closes a circuit from ground $G3$ (by way of contacts $158-159$) through contacts $160-161$; through lamps $e28$, $e31$ and $e34$ in parallel to battery $B3$, causing these lamps to glow and thus indicating to the automatic toll operator that the "B" operator has inserted the plug in the called subscriber's line (or the intermediate trunk to that line). The "B" operator depresses the ringing key associated with the plug, or otherwise signals the subscriber at the proper intervals, breaking contacts $k3-k2$ and $k4-k5$, and making contacts $k1-k2$ and $k5-k6$, which serves to connect the signaling current source, $Z1$, with the subscriber's line through plug $P1$ and jack $J7$. This causes the subscriber's signal device to operate, and upon his removing the receiver from switch hook in responding to closes the line circuit for direct current through his telephone set. The ringing key being released to normal position, current flows from battery $B1$ through the lower winding of relay $R5$; through repeating coil winding $C7$; through contacts $k3-k2$; through tip of plug; through engaging tip spring of jack; through subscriber's line and set back through the sleeve of jack; sleeve of plug; contacts $k4-k5$; through repeating coil winding $C5$; through the upper winding of relay $R5$ to ground $G1$. This current passage actuates relay $R5$. The resistance $T1$ is again shunted out by ground through contacts $40-39$ of relay $R5$, which will cause the current to be augmented along the main line circuit to its original value, causing relay $R32$ to again actuate, incidentally opening its contacts $160-161$, thereby extinguishing lamps $e28$, $e31$, $e34$, indicating to the operator at the automatic toll board the fact that the subscriber has answered. Current also flows from battery $B1$ through sounder $S3$; through lamp $e2'$; through contacts $42-41$; through relay $R1$; through contacts $48-49$ to ground $G1$, causing relay $R1$ to operate. The lamp $e1'$ is extinguished by having its circuit broken through contacts $6-7$. After telephonic service with the subscriber has been completed and the subscriber has replaced his receiver on the gravity switch hook (or the equivalent), incidentally breaking the instrument circuit continuity, relay $R5$ is thus de-energized and returns to its normal position; contacts 39 and 40 are broken, removing the shunt from the resistance $T1$, which latter condition causes the current along the line to be again reduced, causing relay $R32$, Fig. 3, to return to its normal position, also causing lamps $e28$, $e31$ and $e34$ to glow as previously described, informing the operator that the subscriber has replaced his receiver on the gravity hook in its normal position. Although contacts $41-42$ are broken, relay $R1$ is not de-energized, as current now flows from ground $G1$ through contact $49-48$ through relay $R1$; through contacts $1-4$; through contacts $43-42$; through lamp $e2'$; through sounder $S3$ to battery $B1$. Resistance of relay $R1$ is such that current through lamp $e2'$ is reduced below its glowing value. Thus the extinguished condition of lamp $e2'$ when plug $P1$ is in springjack indicates that the called party has responded; this regardless of the glowing or non-glowing state of lamp $e1'$. The automatic toll operator upon observing the signal that the subscriber has hung up, as just described, removes the plug $P2$ from the jacks $J17$, $J18$ or $J19$, as the case

may be. This disconnects the ground G1 from the sleeve of the jack, de-energizing relay R29, causing it to return to normal, breaking contacts 153—154 and 156—157 (contacts of relay R30 are under control of relay R29), which breaks the current along the line as previously traced. This de-energizes relay R8, Fig. 1, and causes it to return to normal position, breaking the circuit of relay R3 through contacts 52—53. Incidentally busy lamps e2, e4, e6, e8, e10, and e12 are extinguished by the opening of contacts 17—18—18'. Current now flows from ground G1 through contacts 17—16; through contacts 5—6; through lamp e1'; through sounder S3, to battery B1, causing the lamp e1' to glow. This is the disconnect signal for the "B" operator. The "B" operator then removes plug P1 from the subscriber's jack J7 (or intermediate trunk jack as the case may be), whereupon all apparatus returns to normal position, as shown in the drawings.

Upon the automatic toll operator inserting plug described into one of jacks J17, J18 or J19, and during the time it is so inserted incident to the telephonic service through the "B" board, the relay R8 is in its operated position, and its dependent relay R3 is also in its operated position; the latter relay cutting off signal device D1 by the opening of contacts 19—20 and 21—22; also opens circuit between the relay R2 and sleeve of jacks J1, J2 and J3 at contacts 23—24, thus precluding the closing of contacts 10—11 and 13—14 of relay R2, which would allow access to the line by the manual toll operator upon inserting a plug into one of the latter jacks. This might disturb a telephonic service from the automatic toll board to the manual exchange through the "B" board. For the same reason contacts 25—26 open the conductor between relay R4 and sleeve of jacks J4, J5 and J6, likewise precluding the possibility of obtaining access to the line and incidentally cutting it off from the "B" board at contacts 34—35 and 37—38. However, if during the course of a service from the automatic toll board, for instance, to a manual subscriber through the "B" board, when plug as described is inserted into either of jacks J1, J2, J3, J4, J5 or J6, upon the automatic toll operator withdrawing the plug to terminate the service, relay R8 will return to its normal position in any event, opening current circuit to relay R3, causing it to return to its normal position, incidentally closing contacts 23—24 and 25—26. The former contacts close circuit of relay R2 to jacks J1, J2, and J3, and the latter contacts likewise close circuit of relay R4 to jacks J4, J5 and J6. In the first case line circuit is opened as regards relay R8 at contacts 11—12 and 14—15, and in the second case at contacts 34—35 and 37—38, thus making it impossible for the

automatic toll operator to obtain access to the "B" board if a plug is inserted in any of the jacks at the manual toll board. The manual toll operator can therefore restrict the automatic toll operator (or any other remote operator) as regards access to the "B" board, and the former operator also is apprised of each service through the "B" board made by a remote operator.

Referring to paragraph b: There are two ways in which an operator at the manual toll board, wishing to call a subscriber in the automatic exchange may do so. One is by means of a calling device d1, associated with one position and which may be connected with various lines by means of the key 193—194—195, while the other is by means of the calling device such as d3 associated with the cord circuit shown in Fig. 5.

Taking up the first case: The operator at the manual toll board notes if multiplied lamps e8, e10 or e12 are glowing. If they are, it would indicate that some other operator at that switchboard had a plug in the line springjack. If lamps (the one lamp before the operator would be the only one observed in practice) are not glowing, the operator would insert plug P2 in any one of jacks J4, J5 or J6. Current will then flow from ground G5 through contacts 180—181; through contacts k17—k16 to the sleeve of the plug; to the sleeve of the jack; through contacts 25—26; through relay R4 to battery B1. This actuates relay R4 which through its contacts disconnects the line terminals A and B from the "B" switching apparatus previously described by opening contacts 34—35 and 37—38. Current will then flow from ground G1 through contacts 27—28; through lamps e1, e3, e5, e7 and e9 and e12 in multiple, causing them to glow and thus indicating to other operators that the line is in use from or to the manual toll board. The operator then manipulates the cord pair listening key in order to close the operator's telephonic circuit from terminal f1, through contacts k22—k21; through repeating coil winding C28; through condenser C; through repeating coil winding C27; through contacts k20—k19; to terminal f2. The telephonic currents in repeating coil windings C28 and C27 act inductively to repeating coil windings C25 and C26; thence through contacts k9—k8 and k10—k11; through tip and ring of plug; through tip and ring of jack; through contacts 30—29 and 32—31; and through repeating coil windings C2 and C4. The telephonic currents act inductively to repeating coil windings C1 and C3; thence through contacts 33—34 and 36—37 to the line terminals A and B. Ascertaining by listening that no other station is using the line, the operator prepares to call the desired number by manipulating the dial on the automatic calling device. Current will now flow from battery

B1 through resistance 192; through contacts 193—194, and then divides in parallel through the repeating coil winding C1 and C3; through contacts 33—34 and 36—37 to terminals A and B; over the toll line conductors in parallel to terminals G and H, Fig. 3; through contacts 153—152 and 156—155; through repeating coil windings C17 and C19; through the two windings of relay R26; through contacts 170—171; through contacts 172—173; to ground G3, actuating relay R26. Current will then flow from ground G3 through contacts 145—146; through lamp e24; to battery B3, causing the lamp to glow, indicating that a call is being made into the automatic exchange. Current also flows from ground G3 through contacts 145—146; through relay R23; to battery B3. This current actuates relay R23, breaking its contacts 124—122, which previously shorted the automatic trunk conductors I and J. The dog 131 is also left free to turn on its pivot 132 under tension of spring 129.

Returning to Fig. 1, the manual toll operator manipulates the calling device key making contacts 194—195 just before breaking contacts 194—193. Current still flows on the line as before, but now through the contacts of the calling device d1, through the resistance r2, to battery B1. The operator then calls the desired figures representing the subscriber's number, by rotating the calling device dial in the manner common to automatic calling. This interrupts the current passing through its contacts into a series of lapses corresponding to the digit called. Relay R26, Fig. 3, returns to its normal position with each current interruption or lapse during the period of the lapse, and current flows from ground G3 through contacts 145—144; through contacts 136—137; through contacts 121—122 of relay R23, which latter relay remains actuated, due to its sluggish or retarded release characteristic; to line terminal J, leading to the so called vertical wire of a so called three-wire first selector of the Strowger type, the operation of which system is well known in the art. This connection is diagrammatically represented in Fig. 4. During the period of lapse while relay R26 is released to normal position, current flows from ground G3 through contacts 119—120; through contacts 147—148; through relay R27 to battery B3. This actuates relay R27, incidentally breaking contacts 150—151 and closes contacts 149—150. Current will then flow from ground G3 through contacts 150—149; through relay R22 to battery B3, actuating relay R22. This movement of relay R22 forces over the pawl arm 127 and the pawl 125 engages the first tooth of the ratchet wheel 130, stepping it up one notch. Ratchet wheel 130 is retained by pawl 131. In the comparatively long interval between the digits, relay R22 remains operated for a comparatively long time. Relay R27 returns to normal position during this interval, followed within an appreciable period of time by relay R22. During the instant while relay R22 remains operated, current flows from ground G3 through contacts 150—151; through contacts 116—115; through contacts 134—133; to line terminal I, leading to the so called rotary wire of the automatic switch as indicated diagrammatically in Fig. 4, thus giving the "rotary" impulse necessary in the so called three wire automatic central office switching mechanism of the type referred to. This same sequence of actions takes place with each digit called, the ratchet wheel 130 stepping up one notch following the last impulse constituting a digit. Each subscriber's number is composed of a certain number of digits fixed by the capacity of the exchange; for example, it being five for a 10,000 line exchange. Supposing, for instance, the call called subscriber's line is numbered 31009, the insulated pin 130' is adjusted to engage the spring 117' to make contacts 117—118 at the end of the fifth step, or on the completion of digit 9. After relay R22 has returned to normal, current flows from ground G3 through contacts 113—112; through contacts 117—118; through relay R24; to battery B3, actuating relay R24. Contacts 140—141 being made, ground is held on contact 117 as long as ratchet wheel 130 remains in the fifth position, which is to say that relay R24 will remain operated throughout the remainder of the service. The operator then rings on the subscriber's line, by calling one or more digits on the calling device d1, interrupting the line circuit correspondingly and allowing relay R26 to return to normal as described. Relay R27 and R22 operate as before. But now, in the instant when relay R27 has returned to normal position and relay R22 is in its actuated position, a circuit may be traced from the ground G3 through contacts 150—151; through contacts 116—115; through contacts 134—135; to terminal J, and on the vertical wire of the trunk to the automatic exchange, as shown in Fig. 4. This gives the vertical impulse necessary to ring a subscriber in a three wire automatic system. When the subscriber responds, an additional organization of relays well known in the art causes the current to flow over line conductors through terminal I; through relay R25; through contacts 114—115; through contacts 134—135; through terminal J to the vertical wire of the trunk to the automatic exchange. A path in multiple with the winding of relay R25 may be traced through repeating coil windings C20 and C18 in series. Current flows from ground G3 through contacts 142—143; through lamp e25, to cause it to glow, indicating to the operator at the automatic toll board that the subscriber has answered. The purpose of this lamp signal de-

vice is to enable the operator at the automatic toll board to know when an operator at a remote manual toll board (or operator at an intermediate toll board) has connection to the automatic exchange, for it is not always advisable to give an operator at a remote toll board unrestricted access to the automatic exchange. This is aside from enabling the operator at the automatic toll board to know the busy or idle state of the line. Incidental to the actuation of relay R25 contact 144' applies ground to free pole of relay R30, causing it to actuate to prevent actuation of relay R29.

15 Armature of relay R26 is controlled by an adjustable tension spring 198 secured between posts 197' and 197, the purpose of which spring is to allow for regulation under varying line conditions, during times of abnormal leakage, for instance.

The register or indicator R is operated by the impulses transmitted by contacts 145-146 as relay R26 operates.

20 A telephonic circuit was previously traced from the cord circuit, Fig. 5, through jacks J4, J5 or J6, Fig. 1, to the terminals A and B of the toll line. This circuit can now be completed as follows: through terminals G and H, Fig. 3, through contacts 153-152 and 156-155; through repeating coil windings C19 and C17; through contacts 138-139; inductively to the repeating coil windings C20-C18 to terminal I of the automatic exchange trunk; and through contacts 114-115; through contacts 134-135; to terminal J of the automatic exchange. The remainder of the circuit to the subscriber is shown diagrammatically in Fig. 4, but need not be shown in detail, as the principles of the circuit are common knowledge to those versed in the art.

Upon the termination of the service, the calling operator removes the plug from the jack and all apparatus in Fig. 1 returns to its normal position, and the current on the toll line conductors is broken. Relay R26, Fig. 3, then returns to normal. Relays R27 and R22 operate as usual. The current in relay R23 is broken by the opening of contacts 145-146. Relay R23 remains operated for an appreciable period, due to its retarded release characteristic, but after the short period it returns to normal. This short circuits terminals I and J by means of contacts 122-124. The current in relay R27 is interrupted by the breaking of contacts 119-120. Relay R27 then returns to normal followed after an appreciable interval by relay R22, giving a ground impulse on terminal I as previously described. Since terminals I and J are connected by a short circuit through contacts 122-124, this gives the short and ground on both wires of the automatic exchange trunk which is necessary to release a call in the three wire Strowger system.

When relay R23 returned to normal the dog 131 was disengaged from the ratchet wheel, which however was held by the pawl 125 as long as relay R22 was operated, but with the release of R22 pawl 125 is disengaged and 70 the ratchet wheel 130 returns to its normal position by the tension of spring 129. This frees the insulated pin 130' and allows contacts 117-118 to break, which in turn releases relay R24. All apparatus is now restored to the normal condition, ready for an incoming or outgoing call of any description.

Toll lines are all subject to accidental ground or to grounded ringing or signaling currents. The consequences to the apparatus by these contingencies is forestalled by controlling the apparatus by means of relay R28, which is connected in a bridge across the toll line through repeating coil windings C17 and C19. Alternating signaling current accidentally applied or directly applied from plug P2 of Fig. 3, for example, will actuate armature of relay R28 first in one direction and then in the other, breaking contacts 170-171 and 172-173 alternately. This in effect 85 disconnects battery from the center of relay R26, preventing its operation or sustainment, the duration of the current being too brief to actuate it or sustain it if actuated.

Another method of automatic calling from 95 the manual toll board to the automatic exchange is where an operator after ascertaining that the line is idle, as in the previous case, inserts a plug into any one of jacks J1, J2 or J3, Fig. 1, as P2, Fig. 5. Current 100 then flows from ground G5 through contacts 180-181; through contacts k17-k16; through sleeve of plug and sleeve of jack; through contacts 23-24; and through relay R2 to battery B1, actuating relay R2. Contact 8-9 is made which causes the busy lamps e1, e3, e5, e7, e9, and e11 to glow, as in the case previously described. The telephonic circuit may now be traced from terminals A and B through contacts 34-35 110 and 37-38; through contacts 11-10 and 14-13; through tip and ring springs of jack; through tip and ring conductors of plug P2, Fig. 5; through contacts k8-k9 and k11-k10; through repeating coil windings 115 C25 and C26 in series; thence inductively to repeating coil windings C27 and C28 to operator's listening key and associated telephone circuits. After listening upon the line the operator manipulates the calling device key, thereby breaking its contacts k16-k17 and k15-k14, making contact k14-k13. Relay R37 was heretofore short circuited by contacts k17-k16, but now operates with current from the sleeve of plug 120 through relay R37 to ground G5. Current now flows from battery B5 through resistance r4; through contacts of calling device d3; through contacts k13-k14; to center C' of repeating coil windings C25-C26, and thence 125 130

to line as previously traced. The operations of calling, and the calling apparatus are identical with those described for the calling device *d1* and associated apparatus, however, 5 with the exception of method of signaling.

When the calling device key is restored, after calling the five digits of the subscriber's number, current flows from battery B5 through relay R38; through contacts 183—182; through contacts *k15*—*k14*; to center of repeating coil C', and thence to line as previously traced. Relay R38 operates, breaking contacts 184—185 and 186—187. To ring or signal the subscriber, the operator depresses toll ringing key, thereby breaking its contacts *k9*—*k8* and *k10*—*k11*, which breaks the current flow to the toll line, causing relay R26, Fig. 3, to return to its normal position as described in connection with calling device *d1*. Relay R38 is de-energized, but remains in its actuated position for an appreciable period of time, due to its retarded release characteristic. Upon relay R38 returning to its normal position, current is again restored to the toll line through contacts *k7*—*k8* and *k11*—*k12*; through contacts 175—176 and 178—179; through contacts 184—185 and 186—187; through the windings *r5* and *r6* of retardation coil to battery B5. This action of relay R38 prevents the interruption of the current for a long enough interval of time to cause the disconnection of the automatic call which would otherwise take place if the operator held the 35 ringing key depressed for too long period of time. When the ringing key is released, relay R38 actuates as before. It is not necessary to detail the operations of calling in the remainder of the operations, as this is identical with those previously described for *d1*. Release is accomplished when plug P2 is removed from the springjack as previously described.

Referring to paragraph *c*: In case *a*, the action of all apparatus in Fig. 1 for an incoming call through the "B" board was fully explained, so it will not be necessary to describe it again. For convenience, however, we will recapitulate the main points of operation. Grounded battery applied to the toll line causes current to flow through relay R8, Fig. 1, and then through the agency of relay R8 connects the toll line with the "B" operator's telephone circuits. When the 50 "B" operator inserts plug P1 in a subscriber's line (or intermediate trunk jack), extra resistance T1 is cut into the line circuit, reducing the current flow. When the called subscriber answers, the resistance T1 is shunted out, thus increasing the current to the former strength. That is, whenever the subscriber's receiver is normally on the gravity hook, current is decreased and whenever the subscriber's receiver is off the gravity hook, current is increased to the original value. With

this in mind we may describe the action of Fig. 2. The intermediate operator, after first ascertaining that busy lamp *e17* is not glowing, plugs into jack J10 with plug P2 and listens in on the line to make certain that the line is not in use between other stations. If it is not in use, the operator changes the plug P2 to jack J8. Current then flows from ground G5 on sleeve of plug P2 through sleeve of jack J8; through relay R14; to battery B2, actuating relay R14. Current then flows from battery B2 through relay R11; through relay R12; through repeating coil windings C10 and C12 in derivation to toll line; thence, as previously described, through relay R8, Fig. 1, which cuts the "B" operator's set off of the line, as previously described.

The subscriber's line is already connected as before and relays R11 and R12 operate the same as relays R31 and R32, Fig. 3, previously described. Current flows from the battery B2 through lamp *e14*; through contacts 59—58 to ground G2, causing lamp *e14* to glow. When the "B" operator inserts P1 into a subscriber's line (or an intermediate trunk jack), the decrease in current previously noted allows relay R12 to return to its normal position. Current then flows from battery B2 through lamp *e13*, glowing it; through contacts 61—60; through contacts 59—58, to ground G2. The glowing lamp, *e13*, indicates to the operator at the intermediate toll board the fact that the "B" operator has the plug P1 in a subscriber's jack and is probably ringing the subscriber, in the usual course. When the subscriber responds, as by removing his telephone from the gravity hook, the increase in current before noted causes relay R12 to again actuate, extinguishing lamp *e13*. Upon completion of the service the lamp *e13* again glows, as subscriber replaces his telephone on the gravity hook. The intermediate operator then withdraws plug P1 from the springjack and all apparatus restores to its normal position as shown in the drawings.

Referring to paragraph *d*: There are two methods by which the intermediate operator may call automatically into the automatic exchange. One is by the use (1) of a calling device *d2* associated with jacks J11 and J13, Fig. 2, while the other (2) is by the use of a calling device *d3* and cord circuit Fig. 5 in connection with jack J8 or jack J9, Fig. 2. In case (1) the operator first ascertains that lamps *e15* or *e17* are not glowing, and then inserts plug P2 into jack J10 or J13 and listens in on the line to make certain the line is not in use between other stations. If it is not in use, the operator inserts plug P2 into jack J11. Current then flows from grounded sleeve of plug previously described through sleeve of jack; through relay R15; to battery B2, actuating relay R15. Current from bat-

- tery B2 reaches ground G2 through contacts 79—78; through lamps e16 and e18 in multiple, causing them to glow as a busy signal. Current from battery B2 also reaches the 5 grounded sleeve of the jack through contacts 93—94; through contacts 91—90; through relay R17; through relay R16 to battery 12, causing relays R17 and R16 to operate. A circuit may now be traced from battery B2 10 through resistance r3; through contacts of calling device d2; through contacts 88—89 to center of seriesed repeating coil windings C13 and C15; thence in parallel through contacts 80—81 and 83—84; through contacts 15 62—63 and 65—66, to toll line by way of its terminals E and F; thence to terminals G and H of the apparatus set at the automatic exchange. Current flowing in this 20 path actuates relay R26, Fig. 3, in the same manner as previously described in case b. The remainder of the calling operations are identical with that in case b, describing the action of the calling device d1, Fig. 1, and need not be again described except that the 25 method of ringing the subscriber is different. To accomplish this the operator depresses ringing key, Fig. 5, breaking contacts k9—k8, k10—k11. Alternating current or other current now flows to ground 30 G5 from generator Z1 through contacts 177—178; through contacts k12—k11; through ring contact of jack J11; through relay R18; through tip of jack J11; through tip of plug P2; through contacts k8—k7; through contacts 35 175—174, to ground G5. This causes the armature of relay R18 to vibrate, opening contacts 93—94 and 90—91, alternately, or in conformance with current derived from generator Z1. This interrupts the current 40 through relays R17 and R16 for the greater part of the time of each application of current upon depressing the ringing key. The only time current flows on the line is while the armature is passing the neutral or normal 45 position, which is for such a small interval of time as to be negligible so far as producing an effective tractive effort on an associated relay. This allows relays R17 and R16 to return to normal, but as R16 has a retarded release characteristic there will be 50 an instance during which contacts 88—89 are broken before contacts 86—87 are made. This action interrupts the current in the main line circuit as previously traced 55 through calling device d2, and which causes relay R26, Fig. 3, to return to normal position for an appreciable period in the same manner as described in case d and rings the automatic subscriber after actuating again. 60 Other details being identical with the previous description, they will be omitted. Upon completion of service, the plug is removed and all apparatus restores to normal position, the automatic subscriber being released as before. 65
- The other method (2) of calling is by means of the calling device d3 and cord circuit, Fig. 5, in connection with jack J9, Fig. 2. The intermediate operator notes that the busy lamps e16 and e17 and e21 are not glowing and then plugs in to jack J10 and listens as before to ascertain if the line is busy, and then inserts plug P2 into jack J9. Current flows from the sleeve of the plug grounded as previously described in case b, through 70 the sleeve of jack; through relay R13, to battery B2, operating relay R13. The toll line is opened by the breaking of contacts 62—63 and 65—66 and that portion of the line towards the automatic exchange is connected 75 with the tip and sleeve contacts of jack J9; through contacts 63—64 and 66—67. The busy lamps e16 and e18 are caused to glow by the closing of contacts 68—69. The operations of selecting the subscriber's line in 80 the automatic exchange with calling device d3, and the subsequent actions of relays R37 and R38, have been fully described before under second action of case b, and need not be repeated, as the actions are similar. 85
- Upon the called subscriber in the automatic exchange responding, relay R25 will be actuated by current projected back along the trunk between the automatic exchange and the automatic toll board. Contact 144' 90 will thus be grounded to G3 through contacts 144'—143—142. This will actuate blocking relay R30, the companion relay to relay R29, precluding access to the line through jacks J17, J18 and J19, incidentally cutting telephonic circuit at contacts 152—153 and 155—156. It also actuates relay R33, which disconnects signal device D4 and causes lamps e22, e23, e26, e29, e32 and e35 to glow. Contacts 143—144 will obtain ground G3 and cause lamp e25 to glow, indicating the response of the subscriber and the fact service is under way. The lamp e24 under control of relay R26 will glow by reason of circuit established to ground G3 through contacts 145—146. Relay R26 remains operated as long as a remote operator has access to the automatic exchange, excepting during the lapses of current while an automatic calling device is being operated to select a subscriber's line in the automatic exchange or while relay R28 is caused to actuate as hereinbefore set forth. During the said brief lapses the lamp e24 will extinguish, but as the duration of the lapses is brief, the lamps appear as glowing constantly, but with a flicker. This flickering is an advantage, since it allows the operator at the automatic toll board to know what is taking place. 100
- Referring to paragraph e: There remains 105 besides the special features described in the preceding cases, the case where the different stations signal and talk over the toll line by the methods more commonly used in present day practice. Most of these methods and 110
- 115
- 120
- 125
- 130

the apparatus for carrying them out are well known in the art and will be merely outlined in this description, but some novelties will be noted.

- 5 (1) Automatic toll operator calling the manual toll board. The automatic toll operator will note condition of busy lamps and if line is free, inserts plug P2 into jack J14, J15 or J16. Current will then flow through 10 relay R30 to grounded sleeve of jack energizing said relay R30 and by superior attraction insures that its companion relay R29 will not operate if a plug should be inadvertently inserted in jacks J17, J18 or J19. 15 Relay R33 also actuates, and by breaking contacts 167—166 and 165—164 disconnects the line signal D4; also closes contacts 163—162 and glows busy signals e22, e23, e26, e29, e32 and e35, indicating to the other operators 20 that the line is busy by reason of a call to or from the automatic toll board. Depressing the ringing key closes the circuit from the toll line through contacts k7—k8 and k11—k12 through contacts 175—174 and 25 178—177 to ringing generator Z1. At the manual toll board this actuates and displays line signal device D1, which the operator at the manual toll board responds to by plugging into jack J3 (or J1 or J2). Subsequent 30 operations follow common practice.
- (2) The automatic station signaling the intermediate station. Operations are identical with the above at the automatic toll board. Ringing current coming in over toll 35 line through contacts 63—62 and 66—65; through contacts 81—82 and 84—85; through contacts 108—109 and 110—111; through relay R19, causing its armature to vibrate. In whichever direction it operates it closes 40 a circuit including contacts 102—103 and through contacts 104—105; through lamps e20 and e19, causing them to glow; and also closes a circuit through relay R20 causing it to operate. Relay R20 locks in the actuated 45 position through its contacts 101—102 and contacts 104—105 of relay R21, causing lamp e20, which is in multiple with relay R20, to continue glowing. At the end of the signaling 50 impulse, contacts 97—98 and 93'—94' are left open, which extinguishes lamp e19. With each succeeding signaling impulse, however, lamp e19 glows in unison with the impulse as long as applied, one set of contacts 97—98 and 93'—94' being closed practically 55 all of the time while the armature of relay R19 is vibrating under signaling current application. When the intermediate operator inserts plug P2 in jack J13, relay R21 is energized by current in the circuit 60 traced from grounded sleeve of cord through sleeve of jack; through relay R21, to battery B2. Signal relay R19 is disconnected from the toll line by the opening of contacts 110—111 and 108—109. Relay R20 is de-energized by the opening of contacts 104—105

and it returns to normal position, incidentally breaking contacts 101—102 and lamp e20 is extinguished. Contacts 106—107 close, causing lamps e21 and e17 to glow. The intermediate toll operator answers by manipulating listening key of cord circuit Fig. 5, etc., etc. Subsequent operations follow common practice.

(3) Intermediate toll operator calling automatic toll board or manual toll board without cutting line. The intermediate operator inserts plug P2 in jack J10 or J13 as in answering a call (2) with same action of apparatus. The operator then depresses the ringing key as in the operation in (2). The 70 ringing current flows to the toll line by circuit path previously traced; through normal path in Fig. 3 previously traced; to tip and ring conductors of jack J16; through contacts 166—167 and 164—165; to line signal device D4, operating it and causing the signal device to display. The operator at the automatic toll board answers by inserting plug P2 in jack J16 (or J15 or J14). Relay R33 75 operates with current in circuit from grounded sleeve of plug; through sleeve of jack; through relay R33 to battery, B3. Signal device D4 is disconnected from the line by opening of contacts 166—167 and 164—165. Busy lamps e22, e23 and e26 are caused 80 to glow through contacts 162—163 closing. Subsequent operations follow common practice.

(4) A portion of the ringing current from the intermediate toll board also find a path 100 as previously described through contacts 34—35 and 37—38; through contacts 11—12 and 14—15; through contacts 20—19 and 22—21; to line signal device D1, energizing it and causing it to display. The manual toll operator responds by inserting plug P2 in jack J3. Current flows in a circuit from the grounded sleeve of plug through sleeve of jack; through contacts 23—24; through relay R2, which actuates, disconnecting all the 105 "B" switching apparatus from the line by the opening of contacts 11—12 and 14—15, likewise disconnecting the signal D1 which was connected behind contacts 11—12 and 14—15. A telephonic circuit is formed from the tip and ring conductors of jack J3 through contacts 10—11 and 13—14; through path previously traced to line. Subsequent 110 operations follow common practice.

(5) Operator at intermediate toll board 120 calling the automatic toll board, cutting the toll line at intermediate station. The operator inserts plug P2 in jack J9. Current in circuit from grounded sleeve of plug; through sleeve of jack; through relay R13 125 to battery B2, actuates relay R13. The toll line is opened by the opening of contacts 62—63 and 65—66. The tip and ring of jack J9 are connected with that portion of the toll line toward the automatic exchange through 130

- contacts 63—64 and 66—67. The busy lamps e16 and e18 are caused to glow by closing of contacts 68—69. Subsequent operations are the same as described in (2).
- 5 (6) Operator at the manual toll board calling either automatic toll board or intermediate toll board. The operator at the manual toll board inserts plug P2, Fig. 5, in jack J1, J2 or J3, Fig. 1. Current flows in circuit from grounded sleeve of plug; through sleeve of jack; through relay R2, as described under paragraph (4). Signaling is accomplished by means of ringing key, Fig. 5, as in other cases previously described. Subsequent operations of answering at automatic toll board or intermediate toll board are the same as described under paragraph (1) and paragraph (4), and need not be described again.
- 10 A plurality of springjacks is shown in each of Figs. 1, 2 and 3. In each case the upper row of springjacks are auxiliary springjacks, and which may be disposed on the switchboard sections remote from the position on which the lower springjacks are located to allow access to the line by any of a number of operators. Obviously, more springjacks may be disposed in multiple relation than shown in the drawings, or all 15 may be omitted without departing from the scope of this invention.
- 15 In the foregoing specifications mention has been made of operating currents passing over the line in parallel. These currents are superposed upon the telephonic currents during sound transmission. It is not necessary to the proper operation or manipulations of the various relays controlling circuit relations that the derived or parallel current flow shall 20 take place. A current applied over only one limb of the line through proper adaptations will answer necessary conditions. The adaptations may be the well known means of deriving a telegraphic circuit from a single 25 limb of a two-limb telephone line. This adaptation is in the parlance of the art of telephony and telegraphy termed a "composite" circuit as distinguished from a "simplexed" circuit wherein both limbs of the line 30 are used in parallel as specifically set forth. Of course, in the present adaptation to automatic telephony the signals transmitted operate electromagnetic devices which in turn control the movement of automatic switches, 35 while in the well known use referred to, the signals transmitted operate a means for operating corresponding electromagnetic devices, the object of which is to produce intelligible 40 manifestations.
- 40 In the specifications and drawings lamp signal devices and electromagnetic signal devices have been referred to. Among the many possible changes and adaptations in the circuits and apparatus, other forms of signal 45 devices may be substituted, or these may be

modified; all of which changes are subordinate to our invention.

The term "ringing" as used herein denotes any means for signaling as applying current of any nature through any means to actuate 50 adapted signal devices.

Having thus described our invention, what we claim as new, and desire to secure by United States Letters Patent, is:—

1. The combination of a subscriber's line 75 in connection with an automatic exchange, a trunk to a toll board, a toll line from said toll board extending to a remote toll board, control means at said remote toll board, the agency of which is to gain connection with the said subscriber's line, a signal device on first said toll board that will display upon manipulations of said means on said remote toll board being made to gain connection with said subscriber's line, and a second signal device on first said toll board that will display in conformance with the response on the said subscriber's line.

2. The combination of an automatic exchange, a trunk line to a toll board, a toll line 80 extending to a remote toll board, a remote toll board, said remote toll board adapted to select a subscriber's line in said automatic exchange, signal devices on first said toll board that will display upon the operator at said remote toll board manipulating its means for selecting a subscriber's line in said automatic exchange, a signal device on first 85 said toll board that will display during the duration of the service between said remote toll board and said subscriber's line, and a second signal device on first said toll board that will display in conformance with the responded or nonresponded condition of the selected subscriber's line.

3. In a trunk circuit, a repeating coil having its winding interposed in the talking conductors of said circuit, a relay interposed between the windings on one side of said repeating coil, a source of current for operating said relay, a supervisory relay and signal controlled thereby, and a resistance for alternating the condition of said signal, controlled by the interposed relay.

4. In a trunk circuit, a repeating coil having its windings interposed in the talking conductors of the trunk circuit, a relay and source of current serially connected between the center terminals of one pair of the repeating coil windings, a supervisory relay 110 and signal controlled thereby, and a resistance for alternating said signal controlled by the first said relay.

5. In a telephone system, a trunk line leading from a manual switchboard to an automatic exchange, automatic apparatus for connecting with telephone lines at the automatic exchange, an operator's cord circuit for connection with the trunk circuit at the manual switchboard, means for applying 120

130

ringing current from the cord circuit to the trunk line, a relay connected to the trunk line responsive to said ringing current, and relay mechanism in the automatic apparatus 6 responsive to the trunk relay for applying ringing current to a connected automatic line.

6. In a telephone system, a trunk line extending from a manual switchboard to an 10 automatic exchange, automatic apparatus at said exchange for connecting to automatic telephone lines thereat, a cord circuit at the switchboard for connection with the trunk line, means for applying signaling current 15 from the cord circuit to the trunk circuit, a relay connected to said trunk at the manual switchboard and responsive to said signaling current, a relay at the automatic exchange end of said trunk circuit thereupon 20 responsive to the first said relay for applying a ringing signal to the conductors leading toward the automatic apparatus.

7. In a telephone system, a trunk line leading from a manual switchboard to an automatic exchange, automatic apparatus for connecting with telephone lines at the automatic exchange, an operator's cord circuit for connection with the trunk circuit at the manual switchboard, means for manually applying ringing current from the cord circuit 25 to the trunk line, a relay connected to the trunk line responsive to said ringing current, and relay mechanism in the automatic apparatus responsive to the trunk relay for applying ringing current to a connected automatic line.

8. A first switchboard and a line extending therefrom to a springjack on a second switchboard, an operator's cord switching 40 circuit at a "B" board contiguous at said second switchboard adapted to be connected with said line, a first signal device on said "B" board, a second signal device on said second switchboard, means at said second switchboard under control of said first switchboard to disassociate the springjack from the line at said second switchboard and actuate the signal device on said second switchboard, together with said signal device on said "B" 45 board.

9. A first switchboard and a line extending therefrom to a springjack on a second switchboard, an operator's cord switching circuit at a "B" board adapted to be connected with said line, a signal device on said "B" board, means at said second switchboard under control of said first switchboard to disassociate the springjack from the line at said second switchboard and actuate the signal 55 device on said "B" board.

10. A first switchboard and a line extending therefrom to a springjack on a second switchboard, an operator's cord switching circuit at a "B" board adapted to be connected to said line, means at said second

switchboard under control of said first switchboard to disassociate the springjack from the line at said second switchboard and means at said "B" board adapted to connect the "B" operator's telephone circuit with said line upon said switching circuit becoming connected with said line. 70

11. A first switchboard and a line extending therefrom to a connecting means on a second switchboard, an operator's cord switching circuit at a "B" board extending from said connecting means and under control of said first switchboard and adapted to be connected with said line, means at said "B" board under control of said first switchboard for connecting the "B" board operator's telephone circuit with said line upon said switching circuit becoming connected with said line. 75

12. A first switchboard and a line extending therefrom to a springjack on a second switchboard, an operator's cord switching circuit at a "B" board adapted to be connected to said line, and means at said second switchboard under control of said first switchboard to effect such connection and also connect the said line with the "B" board operator's telephone circuit. 80

13. A first switchboard and a line extending therefrom to the springjack on a second switchboard, an operator's cord switching circuit at a "B" board adapted to be connected with said line, a first signal device on said second switchboard actuated from said first switchboard independently of other circuit changes relating to said line at said second switchboard, and means under control of said first switchboard for connecting the "B" board operator's telephone circuit with said line. 95

14. The combination of a "B" board in a manual exchange, a toll board, a toll line connected with both said boards, a remote toll board connected on said toll line, means on said remote toll board whereby the operator on the said remote toll board can signal the said first toll board and connect directly into the operator's circuit of the said "B" board at will, signal devices on said first toll board which indicate when said remote toll operator has taken access to the said "B" board. 110

15. The combination of a "B" board in a manual exchange, a toll board, a toll line connected with both said boards, a remote toll board connected on said toll line, means on said remote toll board whereby the operator at the said remote toll board can signal the first toll board or the operator at the said "B" board at will, signal devices on said first toll board that will indicate during time said operator at said remote toll board holds access to said "B" board. 120

16. The combination of a subscriber's line as a part of an exchange, a "B" board in that exchange, a toll board, a toll line connected 125

- with both said boards extending to a remote toll board, means whereby an operator at said remote toll board can signal the said first toll board or can communicate telephonically direct with the operator at the said "B" board, at will, and signal devices on said remote toll board that will evidence or display only if access is obtained to said "B" board.
17. The combination of a subscriber's line as a part of an exchange, a "B" board in that exchange, a toll board, a toll line connected with both said boards extending to a remote toll board, but which may be cut off from said "B" board by means under control of an operator on said toll board when the toll line is in normal state, means on said remote board whereby an operator at said toll board can obtain access to said "B" board or signal said first board normally, signal devices and means controlling same whereby the operator at the remote toll board is enabled to determine if the said subscriber's line when connected at said "B" board with said toll line is responded to or not responded to.
18. The combination of an automatic exchange, a toll board, a trunk line extending from said automatic exchange to said toll board, a toll line extending from said toll board to a remote toll board and to a remote "B" board, the latter as a part of a manual exchange, means whereby the operator at said first toll board is enabled, at will, to signal the operator at said remote toll board or communicate telephonically with the operator at said "B" board, over said toll line, to the end of obtaining telephonic access to a subscriber's line in said manual exchange, means whereby the operator at said remote toll board is enabled to signal, at will, the said first toll board and thereby gain the response of the operator at said toll board or to enable the operator at said remote toll board to select a subscriber's line in said automatic exchange.
19. The combination of a "B" board in a manual exchange, a toll board, a toll line connected at one end with both said boards, a remote toll board on said line, a "B" operator's cord and telephone circuit, means controlled from said remote toll board whereby the operator at said remote toll board can signal at will the first toll board or connect with the "B" operator's circuit direct.
20. The combination of a "B" board in a manual exchange having an operator's cord circuit, a toll board having toll line jacks, a toll line permanently connected with both the circuits of said boards, a remote toll board having access to said toll line by way of two springjacks, normal access to said toll line and toll board being obtained by way of one of said springjacks while access to said "B" board and operator's cord circuit is obtained by way of the other of said springjacks, and means for effecting such alternative connections.
21. The combination of an automatic exchange, a toll line extending from said exchange to two associated springjacks on a remote toll board, other stations on the toll line, connection to one of said two springjacks effecting connection with said line and other stations independent of the automatic exchange, connection to the other of said two springjacks effecting circuit changes for controlling selection into said exchange from said board, and operator's cord switching means for connecting with said springjacks.
22. The combination of a "B" board and a second switchboard, a line extending from a cord circuit at the "B" board and answering jack at the second board to a first and a second spring jack apparatus associated with said line so that a normal connection to the first of said springjacks will operatively connect the line and cord circuit of the "B" board and disassociate the answering jack, and a normal connection with the second of said springjacks will operatively connect the line with the second of said switchboards.
23. A first board and a line extending therefrom to a springjack on a second board, a first switching circuit from said line to a cord circuit at a "B" board and controlled from said first board, means for extending said line circuit to a telephone line circuit by way of said "B" board cord circuit, supervisory signals on said first board and means for actuating same from said telephone line, and means for connecting said line at each board to other lines.
24. A first board and a line extending therefrom to a second board, a switching circuit extending to a cord circuit at a "B" board from said second board, means under control of said first board for connecting said line to the operator's circuit of said "B" board cord circuit, and a signal device on said first board controlled from said "B" board to indicate that access has been obtained to said "B" board, and means whereby said line may be connected to another line at any one of the three boards.
25. A first board and a line extending therefrom to a second board, a switching circuit extending from the line to a cord circuit at a "B" board and controlled from said first board, means at said cord circuit under control of said first board for controlling the connection of said line to the operator's circuit of the said "B" board cord circuit, and means at the said second board for preventing such connection at will, and a signal device on said first board controlled from said "B" board to indicate that access has been obtained to said "B" board.
26. A first board and a line extending therefrom to a second board, a switching circuit extending from the line to a cord circuit

- at a "B" board and controlled from said first board, means at said cord circuit under control of said first board for connecting said line to the operator's circuit of said "B" board
- 5 5 cord circuit and means at said second board for preventing such connection at will, means for preventing access to said line from said second board while said line is in access to said switching circuit, and a signal device
- 10 10 on said first board controlled from said "B" board to indicate that access from said line to said "B" board has been obtained.
27. A first board and a line extending therefrom to a second board, a switching circuit extending from the line to a cord circuit at a "B" board and controlled from said first board, means at said second board under control of said first board for connecting said line to the operator's circuit of said "B" board,
- 15 15 and means at said second board for preventing such connection at will, and means for preventing access to said line from said second board while said line is in access to said switching circuit.
- 25 25 28. A first board and a first line extending therefrom to a springjack on a second board, a first switching circuit extending from the line to a cord circuit at a "B" board adapted to be connected to said first line, a second line and means for connecting said cord circuit to said second line at said "B" board, means under control of said first board to connect said first line to said cord circuit, and a signal lamp associated with said cord circuit
- 30 30 35 which will glow upon said cord circuit becoming connected with said first line and will extinguish when said cord circuit has been connected to said second line and will again glow upon said first line becoming disengaged
- 40 40 from said cord circuit.
29. A line connected to a signal device on a switchboard, said line also connected to an automatic exchange, means adapted to be associated with said line for controlling selection in said exchange, and means for actuating said signal device and a second signal device on said line, the latter which will actuate under control of the called line in the said exchange.
- 50 50 55 60 65 70 75 80 85 90 95 100 105 110 115 120 125 130 30. A line connected to a springjack on a switchboard, said line also connected to an automatic exchange, a signal device on said switchboard, a first means for connecting to said line through said springjack, a second means adapted to be associated with said line for control selection in said exchange, and a third means under control of said second means which will preclude free access to said line from time of first operation of said first means until the response of party on the line called by the selection and will also cause said signal device to actuate and remain actuated until said first means has been returned to normal condition.
- 65 65 81. An automatic exchange, a line leading therefrom to a means adapted for controlling selection in said exchange, a relay connected in a bridge of said line susceptible to signaling currents which upon actuation disassociates said exchange from said line as regards current for controlling selection.
32. An automatic exchange, a line leading therefrom to a means adapted for controlling selection in said exchange, a relay susceptible to signalling current in control of a means adapted to disassociate said exchange from said line as regards current for controlling selection during the time said signal current is acting.
33. An automatic exchange, a line leading therefrom to a means adapted for controlling selection in said exchange, an intermediate current impulse repeating device, a relay associated with said line adapted to be responsive to currents of an abnormal nature as regards currents for controlling selection, the said relay adapted to disassociate operative circuits in said repeating device which normally function in controlling selection.
34. A line upon which is a means for controlling selection leading to a first selector in an automatic exchange, an auxiliary relay on said line, said relay adapted to respond to the first impulse of current for controlling selection over said line, a signal lamp controlled from said relay which will glow responsive to the first selecting impulse and remain glowing until said line has been released for return to normal condition, and means for said releasing.
35. In a telephone system a manual switchboard, an automatic exchange, a toll line connecting said switchboard and exchange, an operator's cord circuit at the manual switchboard, automatic apparatus and telephone lines in the automatic exchange controlled from said operator's cord circuit, a relay in bridge of the toll line operated by the application of ringing current from the cord circuit to effect the application of ringing current to the called line, and means controlled at the manual switchboard for releasing said connection.
36. A telephone system including a manual switchboard and a toll switchboard in an automatic exchange, a toll line connecting said switchboard and toll board, automatic apparatus in the automatic exchange controlled from the manual switchboard for extending connections to lines in the automatic exchange, and a signal at the toll board in the automatic exchange to indicate the toll operator thereat that the remote operator is securing connection with a local subscriber in the automatic exchange.
37. A telephone system comprising a manual switchboard in a manual exchange, a second manual switchboard in an automatic exchange, a toll line connecting said switchboards, a "B" board at the manual exchange

- and a cord circuit thereat connected with said toll line, means whereby the operator at the manual switchboard in the manual exchange may extend connection over said toll line through automatic apparatus to a line in the automatic exchange, and means whereby connection may be extended from a telephone line in the automatic exchange to a telephone line in the manual exchange 5 through said automatic toll board and toll line and the "B" board cord circuit. 38. A telephone system comprising a manual switchboard in a manual exchange, a second manual switchboard in an automatic exchange, a toll line connecting said switchboards, a "B" board at the manual exchange and a cord circuit thereat connected with said toll line, means whereby the operator at the manual switchboard may extend connection 10 over said toll line through automatic apparatus to a line in the automatic exchange, and means whereby connection may be extended from a telephone line in the automatic exchange to a telephone line in the manual exchange 15 through said automatic toll board and toll line and "B" board cord circuit, and a signal at the manual exchange switchboard to indicate to the operator thereat the fact that a telephonic connection is being made to 20 a subscriber's line over said toll line through the "B" board cord circuit. 39. In a telephone system, a telephone line, a calling operator's station at one end of the line, a supervisory signal at the calling station for indicating the condition of a called telephone line connected at the other end of the line, and means for operating said signal operable from the called telephone end only of the line over a simplex circuit including 25 the first telephone line. 40. In a telephone system, a calling station, an automatic exchange including subscribers' telephone lines and selective apparatus for connecting said station with said subscribers' telephone lines in the exchange, a line connecting the calling station and the selective apparatus in the automatic exchange, and means at the calling station and at the automatic exchange for controlling 30 the selecting operation of the selective apparatus over a simplex circuit of the line connecting the calling station and selective apparatus for operating the selective apparatus to connect with a desired subscriber's 35 telephone line. 41. A telephone system including a manual switchboard, an automatic exchange, a toll line connecting said switchboard and said automatic exchange, automatic selective apparatus in the automatic exchange normally in operative relation with the toll line for effecting connection from the toll line to subscriber's lines in the automatic exchange, and control means at the manual switchboard operating 40 over a simplex circuit of the toll line for controlling the selecting operation of the selective apparatus. 42. In a telephone system, a calling station, an automatic exchange including telephone lines and selective apparatus for connecting said station with said telephone lines in the exchange, a line connecting the calling station with a trunk leading to the selective apparatus in the automatic exchange, a translating device interposed between the line and the trunk, means at the calling station for controlling the translating device over a simplex circuit of the line, said translating device in turn controlling the selective operation of the selective apparatus over the physical conductors of the trunk. 43. The combination of a subscriber's line as a part of an exchange, a "B" board in that exchange, a toll board, a toll line connected with both said boards extending to a remote toll board, means whereby an operator at said remote toll board can signal the said first toll board or can communicate telephonically direct with the operator at the said "B" board at will, means at first said toll board for barring said communication with the "B" board, and a signal device on said remote toll board for indicating the state of the last said means. 44. The combination of an automatic exchange, a toll line extending from said exchange to two associated springjacks on a remote toll board, another station on the toll line, connection to one of said springjacks effecting connection with the said line and the said station independent of the automatic exchange, connection with the other of said two springjacks effecting circuit changes preparatory to effecting selective operation in the automatic exchange from said toll board, and an operator's cord switching means for connecting with said springjacks. 45. In a telephone system a near and a remote section of a line, a relay associated with the near section of the line responsive to ringing current from a first source, a second source of ringing current for application to the remote section of the line primarily controlled by the relay, means whereby when ringing current is applied to the near section ringing current from the second source will be applied to the remote section, and automatically applied means for terminating the control of ringing current applied to the remote section. 46. In a telephone system, a telephone line, a calling operator's station at one end of the line, a supervisory signal at the calling station for indicating the condition of a called telephone line connected at the other end of the line, and means controlled by the called line for operating said signal over a simplex circuit of the first telephone line. 47. In a telephone system, an automatic exchange, automatic switch mechanism in the

- exchange, an operator's switchboard, a two-section toll line connecting the switchboard and exchange, a traffic observation station connected intermediate of the said sections, 6 a signal device at said station, a called line in the exchange, an impulse directive device of the switchboard, means for applying the directive device to the toll line, means for operating the switches by the directive 10 device impulses to extend a connection over the toll line to the called line, and means for operating the signal device to indicate to the operator at the said station that a call has been initiated and that the switch mechanism is operating by way of extending the 15 call.
48. A telephone system including a manual switchboard and a toll switchboard at an automatic exchange, a toll line connecting 20 said switchboard and toll board, automatic apparatus in the automatic exchange controlled through the agency of control means at the manual switchboard for extending connections from the toll line to lines in the 25 automatic exchange, a signal at the toll board in the automatic exchange, individual to the toll line operative upon a response being obtained on a called line in the automatic exchange, and effaced upon the responded condition on the called line terminating.
49. A telephone system including a remote manual switchboard and a toll switchboard at an automatic exchange, a toll line connecting said manual switchboard and toll 30 switchboard, automatic apparatus in the automatic exchange controlled through the agency of control means at the manual switchboard for extending connections from the toll line to lines in the automatic 35 exchange, and a signal at the toll switchboard in the automatic exchange individual to the toll line operative at will from a called line.
50. A telephone system including a remote switchboard and a toll switchboard contiguous to an automatic exchange, a remote section of a toll line connecting said remote switchboard and toll switchboard, a near section of the toll line extending to the automatic exchange, automatic apparatus in the 45 automatic exchange directly controlled from the said remote switchboard through a repeater joining the said toll line sections, a signal control means individual to the said near section which will operate a supervisory 50 signal device under control of a called line in the automatic exchange.
51. In a telephone system, a subscriber's line, an automatic exchange, a manual switchboard, a jack-ended trunk line leading from said manual switchboard to said 55 automatic exchange, an operator's station at the automatic exchange, automatic selective mechanism at the end of said trunk line in the automatic exchange for extending connection toward said subscriber's line, a signal 60 device directly connected with and individual to the trunk line at the said operator's station, and relay mechanism for displaying said signal upon response from the said subscriber's line and again actuate said signal upon the subscriber's line returning to its original condition.
52. In a telephone system, an automatic exchange, automatic switch mechanism in the exchange, an operator's switchboard, a two-section toll line connecting the switchboard and exchange, a traffic observation station connected intermediate of the said sections, a signal device at said station, a called line in the exchange, an impulse directive device of the switchboard, means for applying the directive device to the toll line, means for operating the switches by the directive device impulses to extend a connection over the toll line to the called line, means for operating the signal device in correspondence with the directive impulses sent from the directive device effective to the said switches, and means controlled over the called line for operating the signal device to indicate the responded or non-responded condition of the called line.
53. In a telephone system, an automatic exchange, automatic switch mechanism in the exchange, an operator's switchboard, a two-section toll line connecting the switchboard and exchange, a traffic observation station connected intermediate of the said sections, a signal device at said station, a called line in the exchange, an impulse directive device of the switchboard, means for applying the directive device to the toll line, means for operating the switches by the directive device impulses to extend a connection over the toll line to the called line, and means for operating the signal device to indicate to the operator at the said station that a call has been initiated.
54. In a telephone system, an automatic exchange, automatic switch mechanism in the exchange, an operator's switchboard, a two-section toll line connecting the switchboard and exchange, a traffic observation station connected intermediate of the said sections, a signal device at said station, a called line in the exchange, an impulse directive device of the switchboard, means for applying the directive device to the toll line, means for operating the switches by the directive device impulses to extend a connection over the toll line to the called line, and means for operating the signal device in correspondence with the directive impulses sent from the directive device effective to the said switches.
55. In a telephone system, an automatic exchange, automatic switch mechanism in the exchange, an operator's switchboard, a two-section toll line connecting the switchboard and exchange, a traffic observation station connected intermediate of the said sections, a signal device at said station, a called line in 125

- the exchange, an impulse directive device of the switchboard, means for applying the directive device to the toll line, means for operating the switches by the directive device impulses to extend a connection over the toll line to the called line, and means controlled over the called line for operating the signal device to indicate the responded or non-responded condition of the called line.
- 10 56. A telephone system including a manual switchboard and a toll switchboard at an automatic exchange, a toll line connecting said switchboard and toll board, automatic apparatus in the automatic exchange controlled by directive impulses applied through the agency of an impulse control means at the manual switchboard for extending connections from the toll line to lines in the automatic exchange, a signal at the toll board in the automatic exchange operative responsive to the specific control impulses to indicate to the toll operator thereat that the control means is sending impulses and that a connection is in the process of being extended in the automatic exchange responsive to the indicated directive impulses being applied from the control means.
- 15 57. A line leading to an automatic exchange, a call signal device and answering jack connected in bridge of the talking conductors of the line at the automatic exchange, a called line at the automatic exchange, means for association with the first said line for controlling selection in the automatic exchange to extend a connection from the first said line to the called line, and means effective to disassociate the signal device from the said first line consequential to a response being obtained on the called line.
- 20 58. A telephone system including an automatic exchange, a manual switchboard, a toll line extending from said exchange and said switchboard to a calling station, a calling signal device at the manual switchboard controlled at will from the calling station, means at the calling station for directively extending the toll line through switches in the automatic exchange to a called line therein, and automatic means controlled from the called line for incapacitating the said signal device.
- 25 59. A telephone system including an automatic exchange, a toll line extending from said exchange to a calling station, a signal device associated with the toll line controlled at will from the calling station, means at the calling station applied over the toll line for directively extending the toll line through the switches in the automatic exchange to a called line therein, and automatic means controlled from the called line for incapacitating the signal device.
- 30 60. A telephone system including an automatic exchange, a toll line extending from said exchange to a calling station, a signal device connected in a bridge of the talking conductors of the toll line controlled at will from the calling station, means at the calling station applied over the toll line for directively extending the toll line through switches in the automatic exchange to a called line therein, and automatic means controlled over a portion of the talking connection for disassociating the signal device.
- 35 61. A telephone system including an automatic exchange, a toll line extending from said exchange to a calling station, a signal device connected in a bridge of the toll line controlled at will from the calling station, means at the calling station applied over the toll line for directively extending the toll line through switches in the automatic exchange to a called line therein, and automatic means controlled from the called line for disassociating the signal device.
- 40 62. In a telephone system an automatic exchange, a line leading into said exchange from a springjack, an operator's connecting cord and plug for connection with said springjack, a calling signal on the line, means associated with the said cord and plug for applying signaling current effective to the said signal, means for association with the said cord and plug for applying directive impulses effective to switching apparatus in the automatic exchange for extending the said line to a called line in the automatic exchange, and means operative consequent to the second said means being associated with the said cord and plug, to incapacitate the first said means.
- 45 63. In a telephone system a trunk line terminating in a directive switch in an automatic exchange, an operator's springjack and call signal in bridge of said line at the same end, means for seizing said trunk line at the other end, means responsive to such seizure for placing a busy guard discernible at the said springjack, means including the said switch for disconnecting the said call signal, and means of control at the said other end for reconnecting the call signal in bridge of the line.
- 50 64. In a telephone system, a telephone line, a calling operator's station at one end of the line, a supervisory signal at the calling station for indicating the condition of a called telephone line connected at the other end of the line, and means involving a variable resistance device controlled by the called line for operating said signal over a simplex circuit of the first telephone line.
- 55 65. The combination of an automatic exchange, a trunk line to a toll board, a toll line extending to a remote toll board, a remote toll board, means at said remote toll board to select a subscriber's line in said automatic exchange, and a supervisory signal device on first said toll board that will display in conformance with the responded or non-re-

- sponded condition of the selected subscriber's line.
66. In a trunk circuit, a repeating coil having its windings interposed in the talking conductors of said circuit, a relay interposed between the windings on one side of said repeating coil, a source of current for operating said relay, a supervisory relay and signal controlled thereby, and a resistance for altering the condition of said signal controlled over a simplex circuit of the said trunk by the interposed relay.
67. In a telephone system a repeating coil having its windings interposed in the talking conductors of a trunk, a relay interposed between the windings on one side of the repeating coil, a source of current for operating said relay, a supervisory relay and signal controlled by the second said relay, a connected called line, and a resistance for altering the condition of said signal controlled by the interposed relay from the called line over a simplex circuit of said trunk.
68. In a telephone system a trunk line having a springjack at its calling end and an operator's switching cord and plug at the other end, a called line leading to a springjack accessible to the said switching plug, an operator's switching cord and plug for connection with the first said springjack, a supervisory signal device at the calling end controlled by variation of current strength, means responsive to the insertion of the second said plug for causing the application of an operative current effective to the signal device, means responsive to the insertion of the second said plug for causing a change in the strength of current effective to efface the said operation, and means controlled from the called line for altering the strength of current operatively effective to the signal device at will.
69. In a telephone system, a trunk line in two sections inductively related, the first section leading from a springjack on a manual switchboard, and the second section leading to a directive switch in an automatic exchange, lines in the automatic exchange accessible through the said switch directly controlled from the springjack on the first section over both sections, a supervisory signal device, and means including a relay in bridge of the talking conductors of the said second section of the trunk controlled from a called said line in the automatic exchange for operating the said signal device at will.
70. In a telephone system, a trunk line in two sections inductively related, the first section leading from a springjack on a manual switchboard, and the second section leading to a directive switch in an automatic exchange, means for controlling the operation of the said switch from the said springjack, lines in the automatic exchange accessible through the said switch, a supervisory signal device, a relay in a path in bridge of the talking conductors of said second section, a source of current for operating the said relay, a circuit for the said signal independent of the talking conductors of the said first section controlled by said relay, and means whereby the said signal device is operated at will from a connected called line.
71. In a telephone system, a trunk line extending from a manual switchboard to an automatic exchange, automatic apparatus at said exchange for connecting to automatic telephone lines thereat, means for applying signaling current in bridge of the talking conductors of the trunk, a relay controlled by the signaling current connected in bridge of the talking conductors of the trunk at the automatic exchange, and a second relay controlled by the first said relay for applying signaling current to a connected line in the automatic exchange.
72. In a telephone system a trunk line extending from a manual switchboard to an automatic exchange, automatic apparatus at said exchange for connecting to automatic telephone lines thereat, means for applying alternating current in bridge of the talking conductors of the trunk, a relay connected in bridge of the talking conductors of the trunk at the automatic exchange controlled by said alternating current, and a second relay controlled by the first said relay for applying signaling current to a connected line in the automatic exchange.
73. In a telephone system a manual switchboard, an automatic exchange, a trunk line connecting said switchboard and exchange, an operator's cord circuit at the manual switchboard for connection to the said trunk line, automatic apparatus including a connector in the automatic exchange controlled over the trunk line by a sending device, telephone lines in the automatic exchange accessible to the connector, a called one of said lines, a ringing relay in the connector operative to apply signaling current to the called one of said lines, and operator control means in the said operator's cord circuit including a source of alternating current for applying said source of alternating current to the trunk line to operatively control the said ringing relay in the connector.
74. In a telephone system a manual switchboard, an automatic exchange, a trunk line connecting said switchboard and exchange, an operator's cord circuit at the manual switchboard for connection to the said trunk line, automatic linking apparatus including a connector in the automatic exchange controlled over the trunk line by a sending device, telephone lines in the automatic exchange accessible to the connector, a called one of said lines, a ringing relay in the connector operative to apply signaling current to the called line, a relay in bridge

- of the talking conductors of the trunk operative to control the said ringing relay in the connector, and operator control means in the said cord circuit including a source of signaling current for applying said source of current in bridge of the talking conductors of the trunk to operate said relay in bridge of the trunk, whereby said relay in the connector will be operated to apply signaling current to the called line. 70
75. In a telephone system a manual switchboard, an automatic exchange, a toll line connecting said switchboard and exchange, an operator's cord circuit at the manual switchboard, an automatic apparatus having access to telephone lines in the automatic exchange controlled from said operator's cord circuit, a relay in bridge of the talking conductors of the toll line adapted to control the application of signaling current on a called one of said lines, means whereby the operation of the signaling key in the cord circuit will cause the relay to operate and apply signaling current to the called line, and means controlled 80 from the manual switchboard for releasing the connection established with the called line. 85
76. In a telephone system a plurality of links more than one of which terminates in a step-by-step switch at the far end thereof, an operator's cord circuit for connection to a first one of said links, means for directing step-by-step movement of the said switches successively from the first trunk link to interlink the said links in tandem, a ringing relay in the step-by-step switch connected to the remotest link for controlling the application of signaling current to the remotest link, a relay in bridge of the talking conductors at a point between the said cord circuit and the said ringing relay, and a source of current having inductive properties and means for applying it to the talking conductors of the near trunk link operative to 95 the second said relay to control the operation of the said ringing relay. 100
77. In a telephone system a plurality of links more than one of which terminates in a step-by-step switch at the far end thereof, an operator's cord circuit for connection to a first one of said links, means for directing step-by-step movement of the said switches successively from the first trunk link to temporarily interlink the said links in tandem, a ringing relay in the step-by-step switch connected to the remotest link for controlling the application of signaling current to the remotest link, a relay in bridge of the talking conductors of the established connection for controlling said ringing relay, and a source of current and means for applying it in bridge of the talking conductors of the said first link operative to control the said ringing relay. 115
78. In a telephone system, step-by-step switches, other lines, a plurality of trunk links temporarily interlinked in tandem extending from a manual switchboard through the successive step-by-step switches including a said switch accessible to the other lines, a 75 called one of said other lines temporarily interlinked with the said trunk links, a ringing relay in the latter said switch for applying ringing current to the said called line, a control relay connected in a preceding trunk link of the interconnection in control of the said ringing relay susceptible to alternating current, means for applying alternating current to the trunk link to which the control relay is connected to operate the 80 latter said relay, and means whereby the application of alternating current to the link extending from the manual switchboard manifests ringing or signaling upon the called line through intermediate, indirect 85 control. 90
79. In a telephone system a manual switchboard, an automatic exchange, a trunk line connecting said switchboard and exchange, an operator's cord circuit at the manual switchboard for connection to the trunk line, automatic switching apparatus in the automatic exchange controlled over the trunk line, telephone lines in the automatic exchange accessible to the automatic apparatus, a called one of said lines, a relay in bridge of the talking conductors extending between the manual switchboard and the called line, signaling means interposed between the said relay in bridge and the called line controlled by said relay in bridge for applying signaling current to the called line, and means in the said cord circuit for controlling said relay in bridge. 100
80. In a telephone system a manual switchboard, an automatic exchange, a trunk line connecting said switchboard and exchange, automatic switching apparatus having access to telephone lines in the automatic exchange controlled over the trunk line by a sending device, an operator's cord circuit at the manual switchboard for connection with the trunk line, a repeating coil interposed in the talking conductors of the trunk line to form inductively related line sections between the switchboard and the automatic exchange, a relay responsive to alternating current in bridge of the talking conductors of the trunk line section nearest the manual switchboard, a relay in the automatic exchange for applying ringing current to a called line therein controlled by first said relay over a conductor conductively independent of the line section nearest the switchboard, and means in the cord circuit to operatively affect the first said relay whereby the second said relay is caused to operate. 110
81. In a telephone system a manual switchboard, an automatic exchange, a trunk line connecting said switchboard and exchange, 120

- automatic switching apparatus having access to telephone lines in the automatic exchange controlled over the trunk line by a sending device, an operator's cord circuit at the manual switchboard for connection with the trunk line, a repeating coil interposed in the talking conductors of the trunk line to form inductively related line sections between the switchboard and the automatic exchange, a relay in bridge of the talking conductors of the trunk line section nearest the manual switchboard, a relay in the automatic exchange for applying ringing current to a called line therein controlled by first said relay over a conductor conductively independent of the line section nearest the switchboard, and means in the cord circuit to operatively affect the first said relay whereby the second said relay is caused to operate.
82. In a telephone system a manual switchboard, an automatic exchange, a trunk line connecting said switchboard and exchange, an operator's cord circuit at the manual switchboard for connecting to said trunk line, automatic apparatus in the automatic exchange controlled over the trunk line for extending a connection from the trunk line in the direction of a connector and thence to a called line, a relay connected between one of the talking conductors of the connection and ground at a point between the manual switchboard and the connector, a relay in the connector for applying signaling current to the called line under control of the first said relay, and means for secondarily controlling the second said relay over the trunk line.
83. In a telephone system an automatic exchange, a toll line, means for connecting with the toll line at the end remote from the automatic exchange, means applied over the toll line for extending a connection through automatic apparatus in the automatic exchange in the direction of and to a called line therein, a relay in bridge of the talking conductors of the established connection, a relay for applying signaling current to the called line, means interlinking the said relays whereby the second said relay is in control of the first said relay, and means for applying control current to the toll line operative to the first said relay effective to applying signaling current to the called line.
84. In a telephone system an automatic exchange, a toll line, means for connecting with the toll line at the end remote from the automatic exchange, means applied over the toll line for directly extending a connection through automatic apparatus in the automatic exchange in the direction of and to a called line therein, a relay in bridge of the talking conductors of the established connection responsive to alternating current, a relay for applying signaling current to the called line, means interlinking said relays whereby the second said relay is in control of the first said relay, and means for applying control current to the toll line operative to the first said relay effective to applying signaling current to the called line.
85. In a telephone system a manual switchboard, an automatic exchange, a trunk line connecting the manual switchboard and a selector in the automatic exchange, an operator's cord circuit at the manual switchboard for connection with said trunk, means for controlling the said selector in the automatic exchange over the trunk to extend the connection from the trunk in the direction of and to a called line in the automatic exchange, a relay in bridge of the talking conductors of the trunk responsive to alternating current applied from the cord circuit, a called line signalling relay controlled by the first said relay, whereby applying alternating current in bridge of the talking conductors of the trunk will cause signaling current to be applied to a connected called line.
86. A telephone system including a manual switchboard, an automatic exchange, a toll line connecting said switchboard and said automatic exchange, an automatic selective apparatus in the automatic exchange for effecting connection from the toll line to subscribers' lines in the automatic exchange, and control means at the manual switchboard for selectively operating the selective apparatus over a single conductor of the toll line.
87. The combination of an automatic exchange, a toll line extending from said exchange to two associated springjacks on a remote toll board, another station on the toll line, connection to one of said springjacks effecting connection with said toll line and said other station out of operative relation with the automatic exchange, connection to the other of said springjacks effecting circuit changes for controlling selection into said exchange from said toll board, and an operator's cord switching means for connecting with said springjacks.
88. A telephone system including an automatic exchange, a manual switchboard contiguous to said automatic exchange, a toll line extending from the automatic exchange to a remote calling station, a springjack associated with the toll line at the manual switchboard, a plug-ending switching cord for effecting a connection with the toll line through the springjack, means for directly extending the toll line through switches in the automatic exchange to a called line therein, and means controlled by the called line for preventing a connection from being effected from the plug to the toll line.
89. A telephone system including an automatic exchange, a manual switchboard, a toll line extending from said exchange and said switchboard to a calling station, a springjack associated with the toll line at the manual switchboard, a plug-ending switching cord

- for effecting a connection with the toll line through the springjack, means for directively extending the toll line through switches in the automatic exchange to a called line there-in, and automatic means for preventing a connection from being effected from the plug to the toll line. 5
90. In a telephone system including an automatic exchange, a toll line leading from the said exchange to a springjack at a remote station, an operator's switching plug and cord for completing a connection from a calling line to the said toll line through the said springjack, an impulse calling device for association with the said switching cord and plug, means including a simplex control circuit formed of the line and the talking conductors of the said switching cord and plug for directively extending the toll line through the switches in the automatic exchange to a called line therein, and means directly controlled over the line for restoring the switches. 10
91. In a telephone system a toll line extending between two stations, a signal device associated with the toll line at one of the stations, two springjacks associated with the toll line at the other station, a switching cord and plug for effecting connection with the toll line through either springjack at will, and means effective only when a predetermined one of said spring jacks is connected with for disassociating the signal device from the toll line. 15
92. A telephone system including a double jack-ending trunk line leading from a remote station to an operator's connecting plug at a manual exchange, a calling signal at the manual exchange end controlled at will from an operator's switching plug applied to one of the jacks at the remote station, and means at the manual exchange end for disassociating the calling signal responsive to the application of the operator's switching plug to the other jack at the remote station. 20
93. A telephone system including a trunk line leading from a remote station to two switchboards, a calling signal connected with the trunk at each said switchboard, each directively operated from the remote station, means at the switchboards for extending a connection to a called line from the trunk line, means associated with the switchboards controlled at will from the remote station whereby either calling signal can be operated at will, and means associated with the switchboards controlled at will from the remote station whereby either calling signal can be disassociated from the trunk. 25
94. In a telephone system a completed connection from a calling station to a called line in an automatic exchange over a trunk made up of a plurality of sections, an impulse circuit interlinked from the calling station to the automatic exchange involving the trunk sections for controlling automatic switches 30
- in the automatic exchange, impulse relay combinations for repeating control impulses from incoming sections to outgoing sections of the trunk, means at the calling station for initiating the said impulses, and means in the respective relay combinations wherein impulses not exceeding predetermined length are repeated independent of the length of the respective controlling impulses. 70
95. In a telephone system a calling station, a trunk line, an automatic exchange, an impulse circuit in sections for directing switching mechanism in the automatic exchange by way of extending the trunk to a called line therein, an impulse repeater intermediate of two sections of the said impulse circuit, means at the calling station for initiating control impulses effective to the repeater wherein impulses initiated by the calling station are repeated to the automatic exchange mechanism, and means in the repeater wherein impulses not exceeding predetermined length are repeated independent of the length of the impulses received. 75
96. In a telephone system a calling station, a trunk made up of a plurality of sections extending from the calling station to an automatic exchange, a called line in the automatic exchange, an impulse circuit inter-linked from the calling station to the automatic exchange involving the trunk sections wherein sets of repeating relays are interposed in the impulse circuit between the sections thereof, means at the calling station for initiating impulses effective to the automatic switches in the automatic exchange by way of extending a connection from the calling station to the said called line, and means in the respective sets of repeating relays wherein impulses not exceeding predetermined length are repeated independent of the length of received impulses. 80
97. In a telephone system an automatic exchange including common battery automatic selective apparatus and associated lines, another exchange, a trunk line leading from said other exchange to said automatic apparatus, a repeating coil associated with said trunk line, operator control means for operating said selective apparatus over said trunk line for connecting with an automatic line, and a relay operated coincident with the establishment of the connection for introducing said repeating coil into said trunk line regardless of the responded or non-responded condition of the said called line. 85
98. In telephone system, the combination with a toll line entering a central exchange, of a repeater for said toll line at said exchange, a plurality of automatic progressively movable switches, a branch of said toll line extending to one of said switches, a second branch extending to a springjack, and circuits over said branches controlled by said repeater. 90

99. In a telephone system, the combination with a toll line entering a central exchange, of a repeater for said toll line at said exchange, a plurality of automatic progressively movable switches, a branch of said toll line extending to one of said switches, a second branch extending to a springjack, means in said repeater controlled over said toll line for closing an operating circuit over said first branch for said selector, and means in said repeater for placing a guarding condition on said branches. 104. In a telephone system, a subscriber's line, an automatic exchange, a manual switchboard, a jack-ended trunk line leading from said manual switchboard to said automatic exchange, a switching plug, an operator's station at the automatic exchange, automatic selective mechanism at the end of the said trunk line in the automatic exchange for extending connection toward the subscriber's line, a signal device directly connected with and individual to the trunk line at said operator's station, and relay mechanism for displaying said signal upon applying said switching plug into the jack at the end of the trunk line. 70 75 80
100. A first board and a line extending therefrom to a second board, a switching circuit extending to a cord circuit at a "B" board from said second board, means under control of said first board for connecting the line to said cord circuit, a signal device on said first board to indicate if the line has been connected with said cord circuit, and means at said second board for preventing the connection of the line to said cord circuit. 105. In a telephone system, a telephone trunk link extending between a calling station and automatic switches in an automatic exchange, a repeating coil intermediate of the ends of the trunk link, and means directly controlled over the trunk from the calling station for introducing said repeating coil to produce a two-section talking link of said trunk. 85
101. A first board and a line extending therefrom to a second board, a switching circuit extending to a cord circuit at a "B" board from said second board, means under control of said first board for connecting the line to said cord circuit, a signal device on said first board to indicate if the line has been connected with said cord circuit, means at said second board for preventing the connection of the line to said cord circuit, and means effective when the line is connected with said cord circuit to incapacitate the said means at the said second board. 106. In a telephone system, a telephone trunk link extending between a calling station and automatic switches in an automatic exchange, a repeating coil intermediate of the ends of the trunk link independent of control of the switch mechanism in the automatic exchange, and means directly controlled over the trunk from the calling station for introducing said repeating coil to produce a two-section talking link of said trunk. 90 95 100
102. In a telephone system, a trunk line having a springjack at its calling end and an operator's switching cord and plug at the other end, a called line leading to a springjack accessible to the switching plug, an operator's switching cord and plug for connection with the first said springjack, a supervisory signal device permanently associated with the trunk line, means responsive to the insertion of the second said plug for causing the signal device to display if the first said plug is in second said springjack, means for effacing the signal displayed upon a response from the called line, and means on the called line for causing the signal device to again display. 107. In a telephone system, a telephone trunk link extending between a calling station and automatic switches in an automatic exchange, a repeating coil intermediate of the ends of the trunk link independent of control of the switch mechanism in the automatic exchange, means directly controlled over the trunk from the calling station for introducing said repeating coil to produce a two-section talking link of said trunk, and means under control of the calling station for thereafter excluding said repeating coil. 105 110 115
103. In an automatic exchange, a calling line of the exchange, a called line of the exchange, a connecting cord and plug circuit, first and second signaling current sources, a directive control impulse sender, means for normally applying said first signaling current source to the calling line through said plug, means for connecting the said sender to the calling line through said cord and plug for effecting selection of the called line, and means operative coincident to applying the last said means to the cord and plug for displacing said first signaling current source by said second signaling current source. 108. In a telephone system, a trunk extending between a calling station and automatic switches in an automatic exchange, an impulse repeater intermediate of the ends of the trunk link, means in the repeater to translate directive impulses from a first section of the trunk to a second section thereof to operate said switches, and automatic means controlled from the calling station for introducing a repeating coil between the said sections to produce a two-section talking trunk. 120 125
109. In a telephone system, a trunk extending between a calling station and automatic switches in an automatic exchange, an impulse repeater intermediate of the ends of the trunk link, means in the repeater to translate directive impulses from a first section of the trunk to a second section thereof to operate 130

said switches, and automatic means controlled from the calling station for introducing a repeating coil between the said sections to produce a two-section talking trunk responsive to a predetermined number of directive impulses applied from the calling station.

110. In a trunk line, a repeating coil for introduction into the trunk at a point intermediate of its ends to form a two-section talking trunk, a calling station at one end of the trunk, an automatic switch connected at the other end of the trunk, means for directly operating the switch from the calling end, a code switch associated with the trunk controlled only from the calling end independent of the operation of the automatic switch, and means including the said code switch operative responsive to a predetermined plurality of directive impulses from the calling end to introduce the repeating coil.

111. In a telephone system, a trunk link, a repeating coil for introduction into the trunk at a point intermediate of its ends to form a two-section talking trunk, a calling station at one end of the trunk, an automatic switch permanently connected at the other end of the trunk, means for directly operating the switch from the calling end, a code switch associated with the trunk independent of the automatic switch, and means including the said code switch independent of the operation of the automatic switch responsive to predetermined directive control for introducing the repeating coil.

112. In a telephone system a trunk leading to a step-by-step switch, means for directly operating the said switch over the trunk to connect with a called line accessible thereto, a relay in bridge of the talking conductors of the trunk susceptible to alternating current, a relay in the said switch for applying ringing current to the called line from a local source, a source of operating current associated with the first said relay effective to operate the second said relay under control of the first said relay over the talking conductors of the trunk, and means whereby applying alternating current in bridge of the talking conductors of the trunk will cause ringing current to be applied to the connected called line.

113. In a telephone system, a first line arranged to be connected to a second line through connecting mechanism controlled remotely, an operator's switching cord and plug, a source of alternating current, means for connecting said plug with the first line and for operating the switching mechanism for interconnecting the lines, a relay responsive to alternating current connected in bridge of the limbs of the first line, a second relay for directly initiating the primary application of ringing current to the second line controlled by said first relay over an

auxiliary operating conductor, means for applying the source of alternating current through the plug in bridge of the limbs of the first line, and means whereby when alternating current is applied to the first line the second relay will apply ringing current to the second line for a predetermined period, irrespective of the period of application of alternating current to the first line.

114. In a telephone system, a first line arranged to be connected to a second line through connecting mechanism controlled remotely, an operator's switching cord and plug, a source of alternating current, means for connecting said plug with the first line and for operating the switching mechanism for interconnecting the lines, a relay responsive to alternating current connected in bridge of the limbs of the first line, a second relay for directly initiating the primary application of ringing current to the second line controlled by said first relay, means for applying the source of alternating current through the plug in bridge of the limbs of the first line, and means whereby when alternating current is applied to the first line the second relay will apply ringing current to the second line for a predetermined period, irrespective of the period of application of alternating current to the first line.

115. In a telephone system, a first line arranged to be connected to a second line through connecting mechanism controlled remotely, an operator's switching cord and plug, a source of alternating current, means for connecting said plug with the first line and for operating the switching mechanism for interconnecting the lines, a relay responsive to alternating current connected to the first line, a second relay for directly initiating the primary application of ringing current to the second line controlled by said first relay, means for applying the source of alternating current through the plug to the first line, and means whereby when alternating current is applied to the first line the second relay will apply ringing current to the second line for a predetermined period, irrespective of the period of application of alternating current to the first line.

116. In a telephone system, a first line arranged to be connected to a second line through connecting mechanism controlled remotely, an operator's switching cord and plug, a source of alternating current, means for connecting said plug with the first line and for operating the switching mechanism for interconnecting the lines, a relay responsive to alternating current connected to the first line, a second relay for directly initiating the primary application of ringing current to the second line controlled by said first relay, means for applying the source of alternating current through the plug to the first line, and means whereby when alternating current is applied to the first line the second relay will apply ringing current to the second line for a predetermined period, irrespective of the period of application of alternating current to the first line.

- ing current is applied to the first line the second relay will apply ringing current to the second line irrespective of the period of application of alternating current to the first line.
117. In a telephone system, a first line arranged to be connected to a second line through connecting mechanism controlled remotely, an operator's switching cord and plug, a source of ringing current, means for connecting said plug with the first line and for operating the switching mechanism for interconnecting the lines, a relay responsive to ringing current connected to the first line, a second relay for directly initiating the primary application of ringing current to the second line controlled by said first relay, means for applying the source of ringing current through the plug to the first line, and means whereby when ringing current is applied to the first line the second relay will apply ringing current to the second line irrespective of the period of application of ringing current to the first line.
118. In a telephone system, a line leading to a signal device, said line being in sections one and two, a first relay in bridge of the limbs of section one responsive to ringing current, a second relay for directly initiating the application of ringing current to section two to operate the said signal device connected thereon, controlled by said first relay, means for applying current effective to the first relay whereby ringing current is applied to the second section to operate the signal device, and automatically applied means for disconnecting the ringing current from the second section at the termination of a predetermined period of ringing, regardless of the application period of the current to the first section.
119. In a telephone system, a line leading to a signal device, said line being in sections one and two, a first relay connected to section one responsive to ringing current, a second relay for directly initiating the application of ringing current to section two to operate the said signal device connected thereon, controlled by said first relay, means for applying current effective to the first relay whereby ringing current is applied to the second section to operate the signal device, and automatically applied means for disconnecting the ringing current from the second section at the termination of a predetermined period of ringing, regardless of the application period of the current to the first section.
120. In a telephone system, a line leading to a signal device, said line being in sections one and two, a first relay connected to section one responsive to ringing current, a second relay for directly initiating the application of ringing current to section two to operate the said signal device connected thereon, controlled by said first relay, means for applying current effective to the first relay whereby ringing current is applied to the second section to operate the signal device, and automatically applied means for disconnecting the ringing current from the second section at the termination of a predetermined period of ringing, regardless of the application period of the current to the first section.
121. In a telephone system, a near and a remote section of a line, a relay associated with the near section responsive to ringing current from a first source, a second source of ringing current for application to the remote section of the line controlled by the relay, means whereby when ringing current is applied to the near section ringing current from the second source will be applied to the remote section, and automatically applied means for disconnecting the ringing current from the remote section at the termination of a predetermined period of application, regardless of the period of application of current to the near section.
122. In a telephone system, a near and a remote section of a line, a relay associated with the near section responsive to ringing current from a first source, a second source of ringing current for application to the remote section of the line controlled by the relay, means whereby when ringing current is applied to the near section ringing current from the second source will be applied to the remote section, and means for automatically disconnecting the ringing current from the remote section at the termination of a predetermined period of application, regardless of the period of application of current to the near section.
123. In a telephone system, a near and a remote section of a line, a relay associated with the near section of the line responsive to ringing current from a first source, a second source of ringing current for application to the remote section of the line primarily controlled by the relay, means whereby when ringing current is applied to the near section ringing current from the second source will be applied to the remote section, and automatically applied means for removing the near section control of the duration of the application of ringing current to the remote section.
124. In a telephone system, a near and a remote section of a line, a relay associated with the near section of the line responsive to ringing current from a first source, a second source of ringing current for application to the remote section of the line primarily controlled by the relay, means whereby when ringing current is applied to the near section ringing current from the second source will be applied to the remote section, and automatic means for removing the near section control of the duration of the application of ringing current to the remote section.

125. In a telephone system, a near and a remote section of a line, a relay associated with the near section of the line responsive to ringing current from a first source, a second source of ringing current for application to the remote section of the line primarily controlled by the relay, means whereby when ringing current is applied to the near section ringing current from the second source will be applied to the remote section, and automatic means for terminating the control of ringing current applied to the remote section. 70
126. In a telephone system, a near and a remote section of a line, a relay associated with the near section of the line responsive to ringing current from a first source, a second source of ringing current for application to the remote section of the line, primarily controlled by the relay, means whereby when ringing current is applied to the near section ringing current from the second source will be applied to the remote section, and automatic means for disabling the said control function of the relay. 80
127. In a telephone system, a first line connected to a second line through directly controlled selective mechanism, a first and a second source of ringing current, a relay associated with the connected lines responsive to the said first source of current to apply the said second source of current to the said second line, means for directly controlling the said mechanism to connect the lines, means for applying the said first source of current effective to the relay whereby ringing current is applied to the said second line, and automatic means for disenabling the said second ringing current from being further applied to the said second line. 90
128. In a telephone system, a first line connected to a second line through directly controlled selective mechanism, a first and a second source of ringing current, a relay associated with the connected lines responsive to the said first source of current to apply the said second source of current to the said second line, means for directly controlling the said mechanism to connect the lines, means for applying the said first source of current effective to the relay whereby ringing current is applied to the said second line, and means controlled by the relay for disenabling the said second ringing current from being further applied to the said second line. 100
129. In a telephone system, a first line connected to a second line through directly controlled selective mechanism, a source of alternating current and a source of ringing current, a relay connected in bridge of the talking conductors of the connected lines responsive to the said source of alternating current to apply the said source of ring current to the said second line, means for directly controlling the said mechanism to connect the lines, means for applying the said said 110
130. In a telephone system, a first line connected to a second line through directly controlled selective mechanism, a source of alternating current and a source of ringing current, a relay connected in bridge of the talking conductors of the connected lines responsive to the said source of alternating current to apply the said source of ringing current to the said second line, means for directly controlling the said mechanism to connect the lines, means for applying the said source of alternating current effective to the said relay whereby ringing current is applied to the said second line, and means controlled by the relay for disenabling the said ringing current from being further applied to the said second line. 120
131. In a telephone system, a first line connected to a second line through directly controlled selective mechanism, a first and a second source of ringing current, a relay associated with the connected lines responsive to the said first source of current which functions to apply said second source of current to said second line, means for directly controlling the said mechanism to connect the lines, means for applying the said first source of current effective to the relay whereby ringing current is applied to the said second line, and automatic means for disabling the said function of the relay. 130
132. In a telephone system, a first line connected to a second line through directly controlled selective mechanism, a first and a second source of ringing current, a relay associated with the connected lines responsive to the said first source of current which functions to apply said second source of current to said second line, means for directly controlling the said mechanism to connect the lines, means for applying the said first source of current effective to the relay whereby ringing current is applied to the said second line, and means controlled by the relay for disenabling the said function of the relay. 140
133. In a telephone system, an "A" operator's board, a "B" operator's board, a springjack on each said boards, an operator's cord and connecting plug on each said board for cooperation with the companion said springjack, a called line terminating on the springjack on the "B" board, a two-conductor talking and operating trunk line extending between the springjack on the "A" board and the plug on the "B" board, an operator's talking circuit on the "B" board, means controlled over the trunk from the "A" board end for establishing a talking connection between the said operator's talking circuit on 150

the "B" board and the plug on the "A" board responsive to inserting the plug at the "A" board into its companion springjack, and means controlled by the "B" operator for disconnecting the said connection from the "B" board talking circuit and alternatively connecting it through the said "B" board plug and jack to the called line responsive to inserting the plug on the "B" board into its companion said jack.

134. In a telephone system, an "A" board and a "B" board, a springjack on the "A" board, a plug-ending switching cord on the "B" board, a trunk line extending between the first said springjack and the said cord on the "B" board, a switching plug at the "A" board for connection to the companion said springjack, means cooperative responsive to applying the plug at the "A" board into the springjack thereat to effect a connection between the said plugs, a relay at the "B" board end of the trunk, a manually operated circuit closer for the relay, and automatically applied means effective consequent upon withdrawing the plug from the springjack at the "A" board when the circuit closer is in its operated state for disconnecting the trunk from the said cord on the "B" board.

135. In a telephone system, a two-conductor talking and operating trunk line, a pair of springjacks at one end of the trunk line, an operator's connecting plug, a pair of circuit branches at the other end of the trunk line, each springjack corresponding to a specific said branch, and means controlled over the trunk line responsive to inserting the plug into one or the other said springjack at will for effecting an exclusive connection from the said plug to the corresponding said branch wherein the other said branch is maintained disconnected from the trunk line.

136. In a telephone system, a trunk line, two branches for one end of the trunk line, only one of said branches having normal talking connection with the trunk line, means controlled over the other said branch for disconnecting the said normal branch from the trunk line and substituting said other branch therefor, and means controlled over the said normal branch for preventing the said disconnection and substitution.

137. In a telephone system, a two-conductor talking and operating trunk line, two branches for one end of the trunk line, only one of said branches having normal talking connection with the trunk line, means controlled over the other said branch for disconnecting the said normal branch from the trunk line and substituting said other branch therefor, and means controlled over the trunk line for preventing the said disconnection and substitution.

138. In a telephone system, a two-way trunk line, means including operator's equipment and call signals for manually extend-

ing connections over said trunk in either one of two directions, an automatic switch at one end of said trunk, and means for operating said switch over said trunk to extend a connection thereover semi-automatically.

139. In a telephone system, a manual board, a trunk line terminating in said board, a pair of branches for the opposite end of said trunk, one branch terminating in an automatic switch and the second branch terminating in a second manual board, means for controlling said automatic switch over said trunk line, a signal associated with said second manual board, and means for operating said signal over said trunk line.

140. In a telephone system, a trunk line, means for seizing one end of said trunk, a pair of branches for the opposite end of said trunk, an automatic switch connected with one of said branches, a manual jack associated with the other of said branches, a signal associated with said jack responsive to calls over said trunk line, and means for operating said switch over said trunk without operating said signal.

141. In a telephone system, a trunk line, means for seizing one end of said trunk, a pair of branches for the opposite end of said trunk, an automatic switch connected with one of said branches, a manual jack associated with the other of said branches, a signal associated with said jack, means for operating said switch over said trunk without operating said signal, and means for operating said signal over said trunk without operating said automatic switch.

142. In a telephone system, a manual operator's cord circuit, a trunk line having a terminal adapted to be connected with said cord, a pair of branches for the opposite end of said trunk, an automatic switch associated with one of said branches, a manual terminal associated with the other of said branches, a signal associated with said manual terminal to indicate incoming calls, and means by which the operator at said cord circuit can control the operation of said automatic switch over said line without operating said signal.

143. In a telephone system, a manual operator's cord circuit, a trunk line having a terminal adapted to be connected with said cord, a pair of branches for the opposite end of said trunk, an automatic switch associated with one of said branches, a manual terminal associated with the other of said branches, a signal associated with said manual terminal, means by which the operator at said cord circuit can control the operation of said automatic switch over said line without operating said signal, and means by which said operator can operate said signal without operating said automatic switch.

144. In a telephone system, an automatic switch, a plurality of trunk lines divided into

- groups, said switch having one motion to select groups and a second motion to find a line in the selected group, and non-differential means energized over the two sides of a line circuit in parallel, for controlling the operation of said switch. 70
145. In a telephone system, a subscriber's line, an automatic switch, means including a trunk line for extending a connection from 10 said line to said switch, a plurality of trunk lines divided into groups extending from said switch, said switch having one motion to select groups and a second motion to find a line in a selected group, and non-differential means energized over the two sides of said first-mentioned trunk in parallel, for controlling said switch. 75
146. In a telephone system, a trunk line, an automatic switch in which said trunk terminates, a group of trunk lines extending from said switch, and non-differential means energized over the two sides of said first-mentioned trunk in parallel for controlling 15 said switch to connect with an idle one of said groups of trunks. 80
147. In a telephone system, a trunk line, an automatic switch in which said trunk terminates, a bridge across the opposite end of said trunk, a source of current normally connected to a mid-point of said bridge, and means for controlling said switch by intermittently breaking the connection of said source of current with said bridge. 85
148. In a telephone system, a manual exchange, a second exchange, subscribers' lines terminating in said second exchange, a trunk line terminating in said first exchange and extending to said second exchange, means for 20 manually extending a connection from said trunk line to a subscriber's line terminating in said second exchange, and automatic means controlled over two sides of said trunk line in parallel for extending a connection from said trunk line to a subscriber's line terminating in said second exchange. 90
149. In a telephone system, a manual board, a trunk line terminating in said board, a pair of branches for the opposite end of said trunk, one branch terminating in an automatic switch and the second branch terminating in a second manual board, means for controlling 25 said automatic switch over two sides of said trunk line in parallel, a signal associated with said second manual board, and means for operating said signal over a circuit including two sides of said trunk line in series. 110
150. In a telephone system, a line, a simplex circuit associated with said line, a relay, a normally inoperative operating circuit for the 30 relay involving said line and the simplex circuit, an impulse sender, a battery for operating said relay, said simplex circuit having two terminal bridge-sections for bridging the line circuit, each bridge consisting of a resistance conductor, to the mid-point of which the simplex circuit is connected, means for connecting and disconnecting said terminals across the line, a plurality of circuits, and a progressively movable switch associated with said circuits and controlled by 115 said relay to extend a connection from said line to any one of said circuits. 120
151. In a telephone system, a line, a simplex circuit associated with said line, a relay, a normally open operating circuit for the relay involving said line and the simplex circuit, an impulse sender, a battery for operating said relay, said simplex circuit having two terminal bridge-sections for bridging the line circuit, each bridge consisting of a resistance conductor, to the mid-point of which the simplex circuit is connected, means for connecting and disconnecting said terminals across the line, a plurality of circuits, and a progressively movable switch associated with said circuits and controlled by 125 said relay to extend a connection from said line to any one of said circuits. 125
152. In a telephone system, a line, a simplex circuit associated with said line, a relay, a normally inoperative operating circuit for the relay involving said line and the simplex circuit, an impulse sender, a battery for operating said relay, said simplex circuit having two terminal bridge-sections for bridging the line circuit, a plurality of circuits, a progressively movable switch associated with said circuits and controlled by said relay to extend connection from said line to any one of said circuits. 130
153. In a telephone system, a line, a simplex circuit associated with said line, a relay, a normally inoperative operating circuit for the relay involving said line and the simplex circuit, an impulse sender, a battery for operating said relay, said simplex circuit having two terminal bridge-sections for bridging the line circuit, each bridge consisting of a resistance conductor, to the mid-point of which the simplex circuit is connected, means for connecting and disconnecting one of said terminals across the line, a plurality of circuits, a progressively movable switch associated with said circuits and controlled by 135 said relay to extend a connection from said line to any one of said circuits, and release apparatus for restoring the switch controlled by said relay. 140
154. In a telephone system, a line, a simplex circuit associated with said line, a relay, a normally open operating circuit for the relay involving said line and the simplex circuit, an impulse sender, a battery for operating said relay, said simplex circuit having two terminal bridge-sections for bridging the line circuit, each bridge consisting of a resistance conductor, to the mid-point of which the simplex circuit is connected, means for seizing said line, and for closing said 145

operating circuit to render said relay responsive to said impulse sender, a plurality of circuit, a progressively movable switch associated with said circuits and controlled by said relay to extend a connection from said line to any one of said circuits, means for completing a talking circuit via said line and said circuits, and a central battery for supplying current for talking thereover.

155. In a telephone system, a line, manual equipment for extending a connection to said line, manual equipment for extending a connection from said line, a simplex circuit including resistance coils bridged across said line at two points and the two conductors of said line in parallel, an automatic progressively movable switch associated with said line, and means for operating said switch over said simplex circuit.

156. In a telephone system, a line, manual equipment for extending a connection to said line, manual equipment for extending a connection from said line, a simplex circuit including resistance coils bridged across said line at two points and the two conductors of said line in parallel, an automatic progressively movable switch associated with said line, and means for operating said switch over said simplex circuit, said means comprising a relay in said circuit and call mechanism for transmitting current impulses thereover.

157. In a telephone system, a trunk line provided with a manual connective terminal at one end, and a second manual connective terminal and a call signal at the other end, an automatic switch associated with said second terminal and controllable over said trunk line, means including said manual equipment for extending calls over said trunk line in one direction, and means including said first terminal and the said switch for extending calls over said trunk line in the same direction.

158. In a telephone system, a trunk line, operator's equipment comprising manual connective terminals at each end of said trunk line and a call signal at one end thereof for extending calls over said trunk line in one direction manually, and means including the operator's equipment at one end of said trunk line and an automatic switch at the other end of said trunk line controllable thereover for extending calls over said trunk line in the same direction semi-automatically.

159. In a telephone system, a trunk line having at one end two branches terminating, respectively, in an automatic switch and in a manual connective terminal, a call signal associated with said terminal, a second manual connective terminal at the other end of said trunk line, means including operator's equipment and the said terminals and call signal for completing connections over said trunk line manually, and means including operator's equipment and the said second

terminal and automatic switch for completing connections over said trunk line semi-automatically.

160. In a telephone system, a trunk line, operator's equipment for connecting calling lines to said trunk line at one end manually, means at the other end of said trunk line for receiving calls and for extending them to called lines manually, and an automatic switch associated with said last means and controllable over said trunk line for extending connections to called lines automatically.

161. In a telephone system, a trunk line provided with a manual connective terminal at one end, and a second manual connective terminal and a call signal at the other end, an automatic switch associated with said second terminal and controllable over said trunk line, means including said manual equipment for extending calls over said trunk line in one direction, means including said first terminal and the said switch for extending calls over said trunk line in the same direction, and means for rendering the said second connective terminal busy to operators when the said switch is operated.

162. In a telephone system, a trunk line provided with a manual connective terminal at one end, and a second manual connective terminal and a call signal at the other end, an automatic switch associated with said second terminal and controllable over said trunk line, means including said manual equipment for extending calls over said trunk line in one direction, means including said first terminal and the said switch for extending calls over said trunk line in the same direction, a visual busy signal associated with said second terminal and means for actuating said signal when the said switch is operated.

163. In a telephone system, a trunk line, operator's equipment comprising manual connective terminals at each end of said trunk line and a call signal at one end thereof for extending calls over said trunk line in one direction manually, means including the operator's equipment at one end of said trunk line and an automatic switch at the other end of said trunk line controllable thereover for extending calls over said trunk line in the same direction semi-automatically, and means controlled in the operation of said switch for rendering the manual connective terminal at the same end of said trunk line busy to an operator.

164. In a telephone system, a trunk line having at one end two branches terminating, respectively, in an automatic switch and in a manual connective terminal, a call signal associated with said terminal, a second manual connective terminal at the other end of said trunk line, means including operator's equipment and the said terminals and call signal for completing connections over said trunk line manually, means including oper-

- ator's equipment and the said second terminal and automatic switch for completing connections over said trunk line semi-automatically, and means controlled in the operation of said switch for rendering the manual connective terminal at the same end of said trunk line busy to an operator.
165. In a telephone system, a trunk line, operator's equipment for connecting calling lines to said trunk line at one end manually, means at the other end of said trunk line for receiving calls and for extending them to called lines manually, an automatic switch associated with said last means and controllable over said trunk line for extending connections to called lines automatically, and a circuit closed in the operation of said switch for rendering the said trunk line busy to an operator at the same end thereof.
166. In a telephone system, a trunk line, operator's equipment at both ends of said trunk line for extending connections thereover in either direction manually, and means including the said operator's equipment at one end of said trunk line and an automatic switch at the other end of said trunk line controllable thereover for extending connections over said trunk line semi-automatically.
167. In a telephone system, a trunk line, a manual connective terminal and call signal at each end of said trunk line for handling calls thereover manually in either direction, and an automatic switch at one end of said trunk line controllable from the other end thereof for extending connections over said trunk line semi-automatically.
168. In a telephone system, a trunk line, manual equipment including a call signal at each end of said trunk line for receiving calls and for extending them to called lines manually, and an automatic switch at one end of said trunk line controllable thereover for extending connections to called lines automatically.
169. In a telephone system, a trunk line, operator's equipment at both ends of said trunk line for extending connections thereover in either direction manually, means including the said operator's equipment at one end of said trunk line and an automatic switch at the other end of said trunk line controllable thereover for extending connections over said trunk line semi-automatically, and a circuit closed in the operation of said switch for rendering the said trunk line busy to an operator at the same end thereof.
170. In a telephone system, a trunk line, a manual connective terminal and call signal at each end of said trunk line for handling calls thereover manually in either direction, an automatic switch at one end of said trunk line controllable from the other end thereof for extending connections over said trunk line semi-automatically, and a circuit closed in the operation of said switch for rendering the said trunk line busy to an operator at the same end thereof.
171. In a telephone system, a trunk line, manual equipment including a call signal at each end of said trunk line for receiving calls and for extending them to called lines manually, an automatic switch at one end of said trunk line controllable thereover for extending connections to called lines automatically, and a circuit closed in the operation of said switch for rendering the said trunk line busy to an operator at the same end thereof.
172. In a telephone system, a two conductor metallic circuit trunk line terminating at one end in an automatic progressively movable switch, a control circuit for operating and releasing said switch superimposed on the two conductors of said trunk line, and calling mechanism for transmitting current impulses over said control circuit.
173. In a telephone system, a two conductor metallic circuit trunk line terminating at one end in an automatic progressively movable switch, a control circuit for operating and releasing said switch including the two conductors of said trunk line in parallel and a ground return, and calling mechanism for transmitting current impulses over said control circuit.
174. In an automatic telephone system, a trunk line, a jack on the near end of said line, switch mechanism on the far end of said line for extending talking connections from said line, a simplex circuit of said line, an operator's cord and plug, an operator controlled impulse effecting device and switch therefor companion to the cord and plug but independent of said line for directing the operation of the switch mechanism over the simplex circuit, means whereby applying said plug to said jack and operating said switch, will thereby connect said impulse device with said simplex circuit, and means whereby thereafter directly operating the impulse device will correspondingly directly operate the switch mechanism over the simplex circuit.
175. In an automatic telephone system, a trunk line, a fixed terminal on the near end of said line, switch mechanism at the far end of said line for extending talking connections from said line, a superposed circuit of said line, a movable terminal cooperative with said fixed terminal, an operator's impulse effecting device companion to said movable terminal but independent of said line for directing the operation of the switch mechanism over the superposed circuit, means whereby seizing the fixed terminal by the movable terminal will thereby companion said impulse device with said superposed circuit, means for operatively connecting the impulse device with the superposed circuit, and means whereby thereafter directly operating the impulse device will correspond-

ingly directively operate the switch mechanism over the superposed circuit.

176. In a telephone exchange system, an operator's position, a sender, an automatic telephone exchange called subscriber's line circuit, a connecting circuit including a trunk line a repeater, and a train of automatic switches for establishing a connection between said position and said line circuit, said repeater being provided with a repeating coil normally disconnected from said connecting circuit for repeating voice currents and also with means for repeating impulses from said sender to operate said switches, electromagnetic switching means adapted upon energization to connect said repeating coil to said connecting circuit, and means for operating said switching means as soon as connection is established with the called line circuit.
177. In a telephone exchange system, an operator's position, an automatic telephone exchange called subscriber's line circuit, senders therefor, a connecting circuit including a trunk line, a repeater, and a train of automatic switches for establishing a connection between said position and said line circuit, said repeater being provided with a repeating coil normally disconnected from said connecting circuit for repeating voice currents and also with means for repeating impulses from said sender at said operator's position to operate said switches, relays adapted upon energization to connect said repeating coil to said connecting circuit and means for operating said relays as soon as connection is established with the called line circuit.

178. In a telephone exchange system, a calling station, an automatic switch, an impulse sender at said calling station for setting said switch, a repeating coil between said sender and said switch conductively separating said calling station and said switch, and means for automatically connecting said coil in circuit with said calling station and said switch as soon as said switch has been set.

179. In a telephone exchange system, an operator's cord circuit, an automatic switch, an impulse sender associated with said cord circuit for setting said switch, a repeating coil between said sender and said switch conductively separating said cord circuit and said switch, and means for automatically connecting said coil in circuit with said cord circuit and said switch as soon as said switch has been set.

180. In a telephone system, subscribers' telephone lines, a trunk circuit for extending connections from one exchange to another exchange, an operator's switching plug link circuit, the plug consisting of talking conductors and an operating conductor for connecting one of said subscriber's lines to said trunk circuit, a trunk operator's telephone, and means including the operating conductor

controlled over the talking conductors of the trunk circuit in parallel for automatically connecting said operator's telephone with said trunk circuit.

181. In a telephone system, a trunk circuit consisting of exactly two line conductors, an A operator's jack at the near end of said circuit, a B operator's connecting plug at the far end of said circuit, a telephone circuit for the B operator normally disconnected from the trunk circuit, an A operator's switching plug, and means including a circuit involving said two line conductors in parallel responsive to inserting said A operator's plug into said jack for connecting the B operator's telephone circuit into talking relation with the trunk circuit.

182. In a telephone system, a trunk link, an A operator's jack at the near end of said link, a B operator's connecting plug at the far end of said link, a telephone circuit for the B operator normally disconnected from said link, an A operator's switching plug, and means including a circuit involving the conductors of said trunk link in parallel responsive to inserting said A operator's plug into said jack for connecting the B operator's telephone circuit into talking relation with the trunk link.

183. A telephone system comprising telephone lines, a trunk circuit adapted for use in connecting said lines to other telephone lines, a cord circuit for connecting the said first lines with said trunk circuit, an operator's telephone, means for automatically connecting said operator's telephone to the trunk circuit responsive to making connection with the trunk circuit by the cord circuit when connection is to be extended over the trunk circuit to a distant line, and automatic means for disconnecting said operator's telephone responsive to connecting said trunk circuit with one of said other telephone lines.

184. A telephone system comprising telephone lines, a trunk circuit adapted for use in connecting said lines to other telephone lines, a cord circuit for connecting the said first lines with said trunk circuit, an operator's telephone, means for automatically connecting said operator's telephone to the trunk circuit responsive to making connection with the trunk circuit by the cord circuit when connection is to be extended over the trunk circuit to a distant line, and automatic means for disconnecting said operator's telephone responsive to a manual operation by said operator.

185. A telephone system comprising telephone lines, a trunk circuit adapted for use in connecting said lines to other telephone lines, a cord circuit for connecting the said first lines with said trunk circuit, an operator's telephone, means for automatically connecting said operator's telephone to the

trunk circuit responsive to making connection with the trunk circuit by the cord circuit when connection is to be extended over the trunk circuit to a distant line, and automatic means for disabling first said means responsive to connecting said trunk circuit with one of said other telephone lines.

186. In a telephone system, a trunk line, a first operator's connecting plug terminating 10 the far end of the trunk line, a second operator's jack terminating the near end of the trunk line, a switching plug for said second operator for connection to said jack, local lines terminating in respective local jacks 15 accessible from the connecting plug, a telephone receiver circuit contiguous to the remote end of the trunk line for said first operator normally disconnected from the trunk line, automatic means operated over 20 the trunk line responsive only to said second operator inserting the switching plug into said second operator's jack for placing the switching plug in talking relation with said receiver circuit, automatic means operated 25 over the trunk line for indicating to said second operator that said receiver circuit is connected to the trunk line, and means whereby said first operator can manually further extend said talking connection to the local 30 jack of a desired random one of said local lines by means of the connecting plug whereby a talking connection will exist from the switching plug to the desired random local line.

35 187. In a telephone system, a trunk line, a first operator's connecting plug terminating the far end of the trunk line, a second operator's jack terminating the near end of the trunk line, a switching plug for said second operator for connection to said jack, local lines terminating in respective local jacks 40 accessible from the connecting plug, a telephone receiver circuit contiguous to the remote end of the trunk line for said first operator normally disconnected from the trunk line, automatic means operated over the trunk line responsive only to said second operator inserting the switching plug into said second operator's jack for placing the switching plug in talking relation with said receiver circuit, automatic means operated over 45 the trunk line for indicating to said second operator that said receiver circuit is connected to the trunk line, means whereby said first operator can manually further extend said talking connection to the local jack of a desired random one of said local lines by means of the connecting plug whereby a talking connection will exist from the switching plug to the desired random local line, and automatic means made effective by said first operator only during and depending upon the duration of said extended connection to the local jack for disabling first said means.

65 188. In a telephone system, a trunk line, a

first operator's connecting plug terminating the far end of the trunk line, a second operator's jack terminating the near end of the trunk line, a switching plug for said second operator for connection to said jack, local 70 lines terminating in respective local jacks accessible from the connecting plug, a telephone receiver circuit contiguous to the remote end of the trunk line for said first operator normally disconnected from the trunk line, automatic means operated over the trunk line responsive only to said second operator inserting the switching plug into said operator's jack for placing the switching plug in talking relation with said receiver circuit, 75 automatic means operated over the trunk line for indicating to said second operator that said receiver circuit is connected to the trunk line, means whereby said first operator can manually further extend said talking 80 connection to the local jack of a desired random one of said local lines by means of the connecting plug whereby a talking connection will exist from the switching plug to the desired random local line, automatic means 85 made effective by said first operator for disabling first said means, and automatic means for maintaining last said means effective only for the duration of said extended connection to the local jack. 90

189. A telephone system comprising a near and a remote group of telephone lines, a trunk line adapted for use in connecting a random one of the near group of lines to a random one of the remote group of lines, a cord circuit for connecting said random one of said near group of lines with the near end of the trunk line, an operator's telephone contiguous to the remote end of the trunk line, and means for automatically connecting said operator's telephone to the remote end of the trunk line responsive to making connection to the near end of the trunk line by the cord circuit when a connection is to be extended from the remote end of the trunk line to said random line of the remote group. 100

190. A telephone system comprising a near and a remote group of telephone lines, a trunk line adapted for use in connecting a random one of the near group of lines to a random one of the remote group of lines, a cord circuit for connecting said random one of said near group of lines with the near end of the trunk line, an operator's telephone contiguous to the remote end of the trunk line, means for automatically connecting said operator's telephone to the remote end of the trunk line responsive to making connection to the near end of the trunk line by the cord circuit when a connection is to be extended from the remote end of the trunk line to said random line of the remote group, and automatic means for signaling over the trunk line 115 from the remote end to the near end that the 120

125 130

operator's telephone is connected to the trunk line.

191. A telephone system comprising a near and a remote group of telephone lines, a trunk circuit adapted for use in connecting a random one of the near group of lines to a random one of the remote group of lines, a cord circuit for connecting said random one of said near group of lines with the near end 10 of the trunk line, an operator's telephone contiguous to the remote end of the trunk line, means for automatically connecting said operator's telephone to the remote end of the trunk line responsive to making connection 15 to the near end of the trunk line by the cord circuit when a connection is to be extended from the remote end of the trunk line to said random line of the remote group, and automatic means for effecting an auditory signal 20 to the operator at the remote end of the trunk line responsive to said connection to the near end of the trunk line by the cord circuit.

192. A telephone system comprising a near 25 and a remote group of telephone lines, a trunk circuit adapted for use in connecting a random one of the near group of lines to a random one of the remote group of lines, a cord circuit for connecting said random one 30 of said near group of lines with the near end of the trunk line, an operator's telephone contiguous to the remote end of the trunk line, means for automatically connecting said operator's telephone in talking relation to the 35 remote end of the trunk line responsive to making connection to the near end of the trunk line by the cord circuit when a talking connection is to be extended from the remote end of the trunk line to said random line of 40 the remote group, an operator's plug-ending cord terminating the trunk line for extending said connection from the remote end of the trunk line to last said random line, a pair 45 of talking terminals of the plug and an independent operating terminal of the plug, and means including the operating terminal for disconnecting the operator's telephone from the trunk line and for disabling first said means.

193. A telephone system comprising a near and a remote group of telephone lines, a trunk circuit adapted for use in connecting a random one of the near group of lines to a random one of the remote group of lines, a 55 cord circuit for connecting said random one of said near group of lines with the near end of the trunk line, an operator's telephone contiguous to the remote end of the trunk line, means for automatically connecting said operator's telephone in talking relation to the 60 remote end of the trunk line responsive to making connection to the near end of the trunk line by the cord circuit when a talking connection is to be extended from the remote 65 end of the trunk line to said random line of

the remote group, an operator's plug-ending cord terminating the remote end of the trunk line for extending a talking said connection from first said cord circuit over the trunk line to last said random line, a pair of talking conductors of said plug over which said talking connection is extended, and operator controlled automatic circuit means at the remote end of the trunk line and conductively independent of the talking conductors of the plug 70 for disabling first said means.

194. In a telephone system, a group of trunks, the far ends of each of the respective said trunks terminating in an operator's switching cord plug, the said plugs for extending connections from only the corresponding said trunks, a B operator's telephone circuit common to said trunks but normally disconnected therefrom, means for effecting a talking connection to the near end 80 of a random said trunk, and automatic means operated over said random trunk responsive to said connection for thereby connecting the B operator's telephone to said random trunk 85 to extend said talking connection to the B 90 operator's telephone.

195. In an automatic telephone system, a trunk line, a manual jack at the near end of the trunk line for enabling connection to the trunk line, automatic switch mechanism at 95 the far end of the trunk line for extending connections away from the trunk line, an operator's common manual connecting switching link for extending temporary talking connections to the trunk line, a connecting plug for the link cooperative with the jack for extending connections through the link to the trunk line, an impulse sending device for the link independent of the trunk line, a switch for the impulse device individual to 100 the link, means including the impulse device and switch and involving a circuit path comprised of a conductor of the link and a talking conductor of the trunk for directively 105 operating the switch mechanism to extend 110 connections from the link over the trunk line and away from the trunk line at the far end, and means whereby the operation of the switch and the sending of impulses from the 115 sending device effective to the switch mechanism will not appreciably affect the talking connection throughout the link.

196. In an automatic telephone system, a trunk line, a manual jack at the near end of the trunk line for enabling connection to the 120 trunk line, automatic switch mechanism at the far end of the trunk line for extending connections away from the trunk line, an operator's common manual connecting switching link for extending temporary talking connections to the trunk line, a connecting plug for the link cooperative with the jack for extending connections through the link to the trunk line, an impulse sending device 125 for the link independent of the trunk line, a 130

- switch for the impulse device individual to the link, means including the impulse device and switch and involving a circuit path comprised of a conductor of the link and a talking conductor of the trunk for directively operating the switch mechanism to extend connection from the link over the trunk line and away from the trunk line at the far end and means whereby the operation of the switch and the sending of impulses from the sending device effective to the switch mechanism will not disable talking through the link to the trunk. 197. In an automatic telephone system, a trunk line a manual jack at the near end of the trunk line for enabling connection to the trunk line therethrough, automatic switch mechanism at the far end of the trunk line for extending connections away from the trunk line, an operator's common manual connecting cord for extending temporary talking connections to the trunk line, a connecting plug for the cord cooperative with the jack for extending connections from the cord to the trunk line, an impulse sending device for the operator's cord independent of the trunk line, a switch for the impulse device individual to the cord for connecting the impulse device to the cord, and means including the impulse device and switch and involving a circuit path comprised of a conductor of the operator's cord and plug thereof and the talking conductors of the trunk line in parallel for directively operating the switch mechanism to extend connections from the operator's cord over the trunk line and away from the trunk at the far end thereof. 198. In an automatic telephone system, a trunk line, a manual jack at the near end of the trunk line for enabling connection to the trunk line therethrough, automatic switch mechanism at the far end of the trunk line for extending connections away from the trunk line, an operator's common manual connecting cord for extending temporary talking connections to the trunk line, a connecting plug for the cord cooperative with the jack for extending connections from the cord to the trunk line, an impulse sending device for the operator's cord independent of the trunk line, a switch for the impulse device individual to the cord for connecting the impulse device to the cord, and means including the impulse device and switch and involving a circuit path comprised of a conductor of the operator's cord and plug thereof and a talking conductor of the trunk line for directively operating the switch mechanism to extend connections from the operator's cord over the trunk line and away from the trunk at the far end thereof while maintaining a talking connection throughout the operator's cord to the trunk line. 199. In a telephone system, a telephone line, a connecting jack at the near end of the line through which connection to the line is taken, automatic switch mechanism for the far end of the line for extending connection away from the line, a random common operator's connecting cord and plug, said plug cooperative with said jack, an operator's telephone, an impulse sending device, means for connecting said operator's telephone temporarily individual to said random cord and plug, means for connecting said impulse sending device temporarily individual to said random cord and plug, means whereby responsive to thereupon directly operating said impulse sending device will cause said switch mechanism to operate to effect a corresponding extension from said line, and means whereby a talking relation can be maintained from said operator's telephone through said random plug and cord and through said jack to said line while said switch mechanism is being directly operated by said impulse sending device applied through said random cord and plug. 200. In a telephone system, a telephone line, a connecting jack at the near end of the line through which connection to the line is taken, automatic switch mechanism for the far end of the line for extending connection away from the line, a random common operator's connecting cord and plug, said plug cooperative with said jack, an operator's telephone, an impulse sending device, means for connecting said operator's telephone temporarily individual to said random cord and plug, means for connecting said impulse sending device temporarily individual to said random cord and plug, means including a talking conductor of said line whereby responsive to thereupon directly operating said impulse sending device will cause said switch mechanism to operate to effect a corresponding extension from said line, and means whereby a talking relation can be maintained from said operator's telephone through said random plug and cord and through said jack to said line while said switch mechanism is being directly operated by said impulse sending device applied through said random cord and plug. 201. In a telephone system, a telephone line, a connecting jack at the near end of the line through which connection to the line is taken, automatic switch mechanism for the far end of the line for extending connection away from the line, a simplex circuit of said line, a random common operator's connecting cord and plug, said plug cooperative with said jack, an operator's telephone, an impulse sending device, means for connecting said operator's telephone temporarily individual to said random cord and plug, means for connecting said impulse sending device temporarily individual to said random cord and plug, means including said simplex circuit as a link over which said switch mechanism is

- controlled responsive to impulses sent by said impulse sending device whereby responsive to thereupon directively operating said impulse sending device will cause said switch mechanism to operate to effect a corresponding extension from said line, and means whereby a talking relation can be maintained from said operator's telephone through said random plug and cord and through said jack to said line while said switch mechanism is being directively operated by said impulse sending device applied through said random cord and plug. 70
202. In a telephone system, a telephone line, a connecting jack at the near end of the line through which connection to the line is taken, automatic switch mechanism for the far end of the line for extending connection away from the line, a superposed circuit of said line, a random common operator's connecting cord and plug, said plug cooperative with said jack, an impulse sending device, means for connecting said operator's telephone temporarily individual to said random cord and plug, and means including said superposed circuit as a link over which said switch mechanism is controlled responsive to impulses sent by said impulse sending device whereby responsive to thereupon directively operating said impulse sending device will cause said switch mechanism to operate to effect a corresponding extension from said line. 80
203. In a telephone system, a telephone line, a connecting jack at the near end of the line through which connection to the line is taken, automatic switch mechanism for the far end of the line for extending connection away from the line, a superposed circuit of said line, a random common operator's connecting cord and plug, said plug cooperative with said jack, an impulse sending device, means for connecting said operator's telephone temporarily individual to said random cord and plug, means including said superposed circuit as a link over which said switch mechanism is controlled responsive to impulses sent by said impulse sending device whereby responsive to thereupon directively operating said impulse sending device will cause said switch mechanism to operate to effect a corresponding extension from said line. 90
204. In a telephone system, a telephone line, a connecting jack at the near end of the line through which connection to the line is taken, automatic switch mechanism for the far end of the line for extending connection away from the line, a simplex circuit of said line, a random common operator's connecting cord and plug, said plug cooperative with said jack, an impulse sending device, means for connecting said impulse sending device temporarily individual to said random cord and plug, and means including said simplex circuit as a link over which said switch mechanism is controlled responsive to impulses sent by said impulse sending device whereby responsive to thereupon directively operating said impulse sending device will cause said switch mechanism to operate to effect a corresponding extension from said line. 95
205. In a telephone system, a telephone line, a connecting jack at the near end of the line through which connection to the line is taken, automatic switch mechanism for the far end of the line for extending connection away from the line, a superposed circuit of said line, a random common operator's connecting cord and plug, said plug cooperative with said jack, an impulse sending device, means for connecting said impulse sending device temporarily individual to said random cord and plug, and means including said superposed circuit as a link over which said switch mechanism is controlled responsive to impulses sent by said impulse sending device whereby responsive to thereupon directively operating said impulse sending device will cause said switch mechanism to operate to effect a corresponding extension from said line. 100
206. In a telephone system, a telephone line, a connecting jack at the near end of the line through which connection to the line is taken, automatic switch mechanism for the far end of the line for extending connection away from the line, a superposed circuit of said line, a random common operator's connecting cord and plug, said plug cooperative with said jack, a switch directing device, means for connecting said switch directing device temporarily individual to said random cord and plug, and means including said superposed circuit as a link over which said switch mechanism is controlled responsive to said switch directing device whereby responsive to thereupon directively operating said switch directing device will cause said switch mechanism to operate to effect a corresponding extension from said line. 110
207. In a telephone system, a first exchange, a second exchange, a transmission 130

line, automatic switches at the second exchange, means at said first exchange for controlling said switches over one side of the line, a source of alternating current at said first exchange, means at said first exchange for controlling said side of the line to transmit signaling impulses thereover comprising a relay, a key for applying alternating current from said source to said relay to cause it to alternately respond and release in accordance with said alternating current, a second source of battery and contacts included in said side of the line and controlled by said relay to cause the line to be alternately opened and closed and means at the second exchange in said side of the line responsive to said signaling impulses.

208. In a telephone system, a first exchange, a second exchange, a transmission line, a subscriber's line, a signaling device thereat, automatic switches at said second exchange, means at said first exchange for controlling said switches over one side of the transmission line, a source of alternating current at said first exchange, a means for controlling said side of the line to transmit signaling impulses thereover comprising a relay, a key for applying alternating current from said source to said relay to cause it to alternately respond and release in accordance with said alternating current, a second source of battery and contacts included in said side of the line controlled by said relay to cause the line to be alternately opened and closed and means responsive to said impulses of current over said side of the line for actuating said signaling device at said subscriber's line.

Signed by us at Portland, county of Multnomah, and State of Oregon, this 3rd day of June, 1915.

HERBERT M. FRIENDLY.
ARCHIBALD E. BURNS.
